REMOTE CONTROLLING APPARATUS

Lloyd V. Lewis, Edgewood, Pa., assignor to The
Union Switch & Signal Company, Swissvale,
Pa., a corporation of Pennsylvania

Application June 25, 1929, Serial No. 373,675

100 Claims. (Cl. 246—5)

My invention relates to remote controlling apparatus, and particularly to apparatus adapted to be used in a centralized traffic control system for railroads, for controlling a plurality of train governing devices, such as railway switches or signals, from a remote point, such for example, as a train despatcher's office, and for also indicating the condition of such devices at said office.

10 The apparatus of my invention, as herein disclosed, is an improvement upon the apparatus shown and claimed in my copending applications, Serial No. 254,690, filed Feb. 16, 1928, for Railway traffic controlling apparatus, and Serial No. 291,465, filed July 9, 1928, for Remote controlling apparatus, the subject matter of said latter application being shown by British Patent 315,220 accepted October 6, 1930.

15 I will describe one form of apparatus embodying my invention, and will then point out the novel features thereof in claims.

20 In the accompanying drawings, Figs. 1 and 2, when placed side by side with Fig. 1 on the left, form a diagrammatic view illustrating a portion of a train despatcher's office provided with apparatus embodying my invention. Figs. 3 and 4 when placed side by side with Fig. 3 on the left, form a diagrammatic view showing a remote station suitable for co-operation with the apparatus illustrated in Figs. 1 and 2 and also embodying my invention.

25 Similar reference characters refer to similar parts in each of the several views.

30 In the modern operation of railway systems it is sometimes desirable to control a number of traffic governing devices located at spaced points over a considerable stretch of track from a central point, such as a despatcher's office, and also to indicate at the control office, the condition of each of these devices. The traffic governing devices are here illustrated as switches and signals, each switch with the corresponding complement of trackway signals being considered as one station, and a plurality of stations being controlled from the despatcher's office indicated in the drawings on Figs. 1 and 2. The despatcher's office and all of the remote stations, are connected together by means of a normally closed line circuit including two line wires D1 and D2 which extend throughout the system. The line circuit is normally supplied with energy from a line battery N located at the despatcher's office, and under normal conditions, the line circuit is closed through the winding of a line relay at each station and at the office. Each line relay

35 is designated by the reference character R with a prefix corresponding to the location. A transmitting relay is provided for each station and the despatcher's office, and a master relay is also provided for each station and for the despatcher's office. Each transmitting relay is designated by the reference character T, and each master relay is designated by the reference character M, with appropriate prefixes referring to the location. Each master relay M is controlled, as will be explained hereinafter, in such manner that the relay is normally de-energized and is arranged to be energized only when a code originating in the apparatus associated with such master relay is being transmitted over the line circuit. At each remote station, the line circuit includes a back contact of the master relay and when the associated master relay is energized, the portion of the line beyond that station is disconnected and the line circuit is completed to the despatcher's office over a back contact of the corresponding transmitting relay. At the despatcher's office, the line circuit does not include a contact of the master relay, but passes directly over a back contact of the transmitting relay.

40 The control of the various parts is accomplished by means of code signals transmitted from the despatcher's office or from any remote station to the line circuit including line wires D1 and D2. Each code is made up of a plurality of impulses each of which impulses is produced by opening the line circuit for a relatively short or long interval of time and again closing the line circuit for a short interval. The first impulse of each code is a locking impulse, the function of which will be described hereinafter. Certain of the impulses following the locking impulse in each code are used to select the station or the corresponding panel at the office, the number of such station or panel selecting impulses required for this purpose depending upon the number of stations to be controlled from the despatcher's office. In illustrating my invention, I have assumed that twelve stations are to be controlled from the despatcher's office, and with this arrangement, seven station selecting impulses are required. The next impulses in each code are used to select the particular operations to be performed at the selected station or panel, and with the apparatus here illustrated I require four impulses for this purpose in control codes originating at the despatcher's office for controlling apparatus at the several stations. In indication codes originating at the station for

informing the operator at the office of the condition of apparatus at the stations, seven impulses are necessary to select the particular operations. The last impulse of each code accomplishes the 5 operation of the devices at the selected station or panel, and also restores the apparatus to normal to prepare it for the reception or transmission of additional codes. With the arrangement here illustrated, therefore, each control code originating 10 at the despatcher's office contains thirteen impulses, and each indication code originating at a remote station contains sixteen impulses, certain of which are prolonged to accomplish different purposes as will appear hereinafter.

15 For purposes of simplicity, I have illustrated only one remote station complete in the drawings, and have shown only that portion of the despatcher's office equipment necessary for the control and indication of this one station, but it will 20 be understood, of course, that the other eleven stations are similar to station No. 1, here illustrated, and that the additional equipment required at the despatcher's office will simply duplicate a portion of the equipment here shown.

25 Referring now particularly to Fig. 4, there is located at station No. 1 a stretch of railway track, the rails of which are designated by the reference characters l and l^a . These rails are divided, by means of insulated joints 2, to form a track section 30 $b-f$. This section is provided with a switch 3 of the usual form communicating with a siding r . The track rails adjacent the section $b-f$ are divided to form a plurality of approach track sections $a-b$, $d-e$ and $f-g$. The main track section 35 $b-f$, and each approach track section is provided with a source of track circuit current, such as a battery 4, connected across the rails adjacent one end of the section, and a track relay connected across the rails adjacent the other end of the 40 section. The track relay for the section containing the switch 3 is designated lTR and the track relay for approach section $a-b$ is designated lRA . Relays $lLBA$ and $lLAA$ are the track relays for approach sections $d-e$ and $f-g$, respectively.

45 Eastbound traffic over the switch 3 is controlled by two signals lRA and lRB , which as here shown are mounted upon the same mast, and westbound traffic over the switch 3 is controlled by signals lLB and lLA . The signals may be of any suitable form, and as here shown are of the usual semaphore type.

The switch 3 operates a plurality of circuit controllers 7, 8, 9 and 10 which are arranged to assume one position or another in response to the 50 position of switch 3 in accordance with usual practice. Switch 3 is in turn controlled by a motor m comprising an armature 32 and a field 34. It is also desirable to arrange the motor for 55 manual operation and for this purpose the switch is provided with what is known as a dual selector mechanism forming no part of my present invention and not shown in the drawings, but comprising two contacts 5 and 6 which are normally 60 closed, and which are arranged to be opened when the dual selector mechanism is placed in condition for manual operation of the switch. The motor m is controlled in part by two route selecting stick relays $lNWS$ and $lRWS$ which are controlled as 65 will be explained hereinafter in accordance with control codes received from the despatcher's office.

70 Associated with the track relay lTR is a track repeater relay lTP , the circuit of which includes contact 5 of the dual selector mechanism of switch 3 and front contact 11 of track relay lTR . The

repeater relay lTP is therefore deenergized when section $b-f$ is occupied or when the switch 3 is under manual control.

The signals at station No. 1 are controlled in part by two traffic direction controlling stick relays lLH and lRH , responsive to control codes received from the despatcher's office as will be explained hereinafter. The two traffic direction controlling relays lLH and lRH control a plurality of signal control relays, one for each signal, 10 and each designated by a reference character formed by adding H to the reference character for the corresponding signal.

The reference character lX designates a back lock relay which is energized only when all of the 15 signals governing traffic over switch 3 are at stop. The circuit for this relay may be traced from terminal B of a source not shown in the drawings, through contact 21 operated by signal lRB , contact 22 operated by signal lRA , contact 23 operated by signal lLA , contact 24 operated by signal lLB , and winding of relay lX , back to terminal C of the same source.

Station No. 1 is also provided with a locking relay lV which is controlled in part by the track 25 relays of the approach sections and in part by a manually operable key release k . The relay lV is normally energized over a stick circuit which may be traced from terminal B, over front contact 13 of relay $lLBA$, front contact 14 of relay $lLAA$, front contact 15 of relay lRA , front contact 16 of relay lV and winding of relay lV to terminal C. Back contact 17 of signal control relay $lLBH$ is connected in parallel with front contact 13 of relay $lLBA$, back contact 18 of signal control relay $lLAH$ is connected in parallel with front contact 14 of relay $lLAA$, and back contacts 20 and 19 of signal control relays $lRAH$ and $lRBH$, respectively, are connected in series across front contact 15 of relay lRA . It is plain, therefore, that 40 the stick circuit for relay lV is normally closed, but that if a train enters any of the approach sections leading into section $b-f$, the opening of the corresponding approach relay will break the stick circuit for relay lV , provided the corresponding signal control relay is energized to clear the appropriate signal. After relay lV has once become de-energized, it can be picked up by the de-energization of relay lTR , whereupon, current is supplied to relay lV , over back contact 12 of 50 relay lTR , or the key release k may be operated to supply current to relay lV over a reverse contact 50 of the key release k . The control of relay lV is in accordance with standard practice for the control of approach locking relays in systems of 55 the type here contemplated, and the operation of this relay will be apparent from the drawings without further explanation.

For the actual control of switch motor m , two electromagnetic contactors lNW and lRW are 60 controlled by the relays $lNWS$ and $lRWS$. As shown in the drawings, the switch 3 occupies its normal position, and relay $lNWS$ is energized. In explaining the operation of the switch motor, I will assume that relay $lNWS$ becomes de-energized and relay $lRWS$ becomes energized. When this happens, front contact 28 of relay $lRWS$ becomes closed. The contactor lRW is provided with a circuit which may be traced from terminal B, over front contact 25 of relay lX , front 70 contact 26 of relay lV , front contact 27 of relay lTP , front contact 28 of relay $lRWS$, contact 8-8^a operated by switch 3, and winding of contactor lRW to terminal C. It will be plain that the contactor lRW can not become energized un- 75

less all signals are at stop, the approach locking is released, and the main track section $b-f$ is unoccupied. When contactor IRW becomes energized, current flows from terminal B, through heater 29 of a thermo-sensitive relay $h1$, front contact 31 of contactor IRW , armature 32 of motor m , front contact 33 of contactor IRW , field 34 of motor m , and contact 6 of the dual selector mechanism of switch 3 to terminal C. The motor m is then operated to move the switch to its reverse position. When the switch attains its full reverse position, the opening of contact 8-8^a interrupts the circuit for contactor IRW and de-energizes motor m . In similar manner, the switch 3 may be restored to its normal position by energizing relay INWS . The circuit for contactor INW passes from terminal B, over front contact 25 of relay IX , front contact 26 of relay IV , front contact 21 of relay ITP , front contact 35 of relay INWS , contact 7-7^b operated by switch 3, and winding of contactor INW to terminal C. When contactor INW becomes energized, current flows from terminal B, through heater 29 of thermo-sensitive relay $h2$, front contact 36 of contactor INW , armature 32 of motor m , front contact 31 of contactor INW , field 34 of motor m , and contact 6 on the dual selector mechanism of switch 3 to terminal C. When the motor m is energized over the circuit just traced, the motor is operated to drive the switch 3 to its normal position. When the switch has attained its full normal position, the opening of contact 7-7^b interrupts the circuit for contactor INW , which therefore opens its front contacts to de-energize motor m . The purpose of thermo-sensitive relays $h1$ and $h2$ will be described hereinafter.

The reference character IKR designates a switch indication relay which is controlled jointly by the relays INWS and IRWS , and by contacts actuated directly by the switch 3. The indication relay IKR is a polarized relay and with the parts occupying the positions in which they are illustrated in the drawings, current flows from terminal B, over back contact 38 of relay IRWS , front contact 39 of relay INWS , contact 9-9^a operated by switch 3, winding of relay IKR , and contact 10-10^a operated by switch 3 to terminal C. The current supplied to relay IKR , under these conditions, energizes the relay in its normal direction so that its polar contacts are swung to the left. If relay IRWS has been energized to move the switch to its reverse position, the circuit for relay IKR will then pass from terminal B, over back contact 39 of relay INWS , front contact 38 of relay IRWS , contact 10-10^b, winding of relay IKR , and contact 9-9^b to terminal C. The current then supplied to relay IKR will energize the relay in its reverse direction so that the polar contacts of the relay will be swung to the right. It should be pointed out, however, that if the switch control relays INWS and IRWS are both de-energized simultaneously, or if the position of the switch does not correspond with the condition of the switch control relays, the indication relay IKR will be de-energized.

The signal control relays ILAH , ILBH , IRAH and IRBH are controlled jointly by the traffic direction controlling stick relays ILH and IRH and by the switch indication relay IKR . For example, when relay ILH is energized to permit traffic moves from east to west, front contact 40 of this relay is closed, and if the switch 3 is then normal so that relay IKR is energized in

the normal direction, current flows from terminal B, over front contact 40 of relay ILH , front contact 41 of indication relay IKR , normal contact 42 of indication relay IKR and winding of relay ILAH to terminal C. When relay ILAH is energized, current is supplied to the operating mechanism of signal ILA , over front contact 43 of relay ILAH so that signal ILA is then cleared to permit westbound traffic to pass over the switch in its normal position. If, however, the switch 3 is reversed when relay ILH becomes energized, the indication relay IKR is reversed, and relay ILBH is then energized over front contact 40 of relay ILH and front contact 41 and reverse contact 42 of relay IKR . The closing of front contact 44 of relay ILBH completes a circuit for the operating mechanism of signal ILB which signal is then cleared to permit westbound traffic to proceed over switch 3 in its reverse position. In similar manner, when relay IRH is energized, and indication relay IKR is energized in its normal direction, relay IRAH is energized over front contact 45 of relay IRH , and front contact 46 and normal contact 47 of relay IKR , and when relay IRAH is energized, current is supplied over front contact 48 of this relay to operate the signal IRA to its clear position. Finally, if relay IKR is energized in its reverse position when relay IRH is energized, relay IRBH is picked up over front contact 45 of relay IRH and front contact 46 and reverse contact 47 of relay IKR . Current is then supplied over front contact 49 of relay IRBH to clear signal IRB . It should be noted that if relays ILH and IRH are both de-energized, all signals will be at stop. Furthermore, all signals are put to stop by the de-energization of relay IKR as a result of any of the conditions previously mentioned in describing the control circuit for this relay, or by the opening of front contact 192 of track relay 40 ITR .

In actual practice, the signals may be "semi-automatic" that is to say, they may be moved only from their stop positions to their caution positions by the apparatus herein shown and described, and may then move automatically from caution to clear under control of traffic conditions in the territory adjacent the portion of track shown in the drawings.

The route stick relays INWS and IRWS and the traffic direction stick relays ILH and IRH are controlled by two manually operable levers Ip and Iq located on a suitable panel at the dispatcher's office, as shown in Fig. 2. This panel is individual to station No. 1 and in addition to the two control levers is provided with a plurality of indication lamps by means of which the condition of the apparatus at station No. 1 is indicated. Of course, a similar panel is provided for each of the other stations. The control panel for each station is also provided with a starting button each designated by the reference character OP with a suffix corresponding to the panel. Associated with each main panel is also an approach panel which is provided with an indication lamp for giving visual information concerning the condition of certain apparatus not conveyed by indication apparatus on the main control panel.

As stated above, the codes delivered to the line circuit are made up of impulses formed by briefly opening the circuit. Since the line relays R at the office and at each remote station are all included in series in the line circuit, each such impulse causes each line relay to become de-ener-

gized, and when the line circuit is again closed, the line relays all become energized. Each line relay controls a chain of counting relays here shown as seven in number and each designated 5 by the reference character B with a distinguishing prefix corresponding to the location and with a suffix corresponding to its position in the chain. Referring particularly to the apparatus shown in Fig. 1, line relay OR controls a chain of counting relays OB₁, OB_{1a}, etc. The alternate relays 10 of the chain, identified by the suffixes 1, 2, 3, and 4, control the various circuits for transmitting and receiving the successive code elements, while the intervening relays, identified by the suffixes 15 1a, 2a, etc., are transfer relays which operate during the intervals between code elements. Each line relay also controls a second chain of counting relays also seven in number and each designated by the reference character C with a prefix 20 corresponding to the location and a suffix designating the position in the chain. The purpose of the second counting chain is to enable the "B" relays of the first chain to be employed repeatedly, thereby decreasing the total number of 25 counting relays required. The alternate relays of the second chain, identified by the suffixes 1, 2, etc., are group relays, one being energized for each cycle of operation of the relays of the first chain, while the remaining relays of the second 30 chain, identified by the suffixes 1a, 2a, etc., are transfer relays which operate during the intervals between the cycles of operation of the relays of the first chain. The relays of the second counting chain are controlled by the associated 35 line relay in such manner that in response to repeated operation of the line relay the relays of the "B" chain are first energized and de-energized successively with relay OC₁ energized, and the B relays are then successively energized and 40 de-energized a second time with relay OC₂ energized, and the same operation is repeated with relays OC₃ and OC₄. Associated with each set of counting relays are three slow-releasing relays designated by the reference characters K, J and Ka, with prefixes corresponding to the 45 location. At the despatcher's office, an additional slow releasing relay OJP is also provided.

The operation of the system depends to some extent upon the time required for the operations 50 of certain relays and for purposes of explanation I have assumed definite values for certain parts, but it should be understood that these values are not essential, but are mentioned only by way of 55 illustration. It is desired that the parts should operate as rapidly as possible and for measuring the intervals required for certain functions the ordinary unit of one second is too long to be convenient. For purposes of reference, therefore, it is convenient to measure these time intervals by referring them to cycles of alternating 60 current of commercial frequency, such as 60 cycles per second. With this explanation in mind, I shall assume that the pick-up times for all relays are substantially the same and equal approximately one cycle of alternating current of a frequency of 60 cycles per second. For convenience in manufacture, I propose to construct the relays with similar parts and to adjust the release times of certain relays by variation in the air gaps 65 and by connecting asymmetric units in parallel with the relays. These asymmetric units are each designated by the reference character x and it will be seen that asymmetric units are connected in parallel with certain ones of the relays, as for 70 example, relays OK and OJ at the despatcher's 75

office. The relays which do not have asymmetric units connected across them are adjusted to release practically instantaneously, and this applies to the line relays R. The transmitting relays T, the master relays M, and the counting 5 relays B and C release in 4 cycles while relays OJ and OK at the office and all relays K at the stations have release times of approximately 12 cycles. Relay OK_a at the office has a release 10 time of 16 cycles. Relays J at the several stations have longer release times than the corresponding relay OJ at the office, and I will assume that the release times of the station relays "J" are 16 cycles. The relays Ka at the stations also have slower releasing characteristics than 15 relay OK_a at the office, the relays Ka at the stations being assumed to release in 20 cycles. Relay OJP at the office has a release time of 8 cycles.

As will be described in detail hereinafter the 20 normal length of each impulse of each code, that is, the interval during which the line circuit is open, is approximately 8 cycles and successive impulses are separated by intervals also of approximately 8 cycles during which the line circuit 25 is closed. Under certain conditions, however, some of the impulses in each code are prolonged as will be explained in detail as the description proceeds. With these preliminary remarks in mind, I will now describe the operation of the 30 counting relays at the despatcher's office in response to a code in the line circuit.

Under normal conditions, all counting relays are de-energized and relays OK, OJ, OJP and OK_a are also de-energized. Relay OR, is of course, energized, because the line circuit is normally closed. The first impulse of the code de-energizes relay OR, thereby closing back contact 51 and completing a pick-up circuit for relay OC₁, over back contact 51 of relay OR, and back contact 52 of relay OK. Relay OC₁ therefore becomes energized. The de-energization of relay OR also completes a pick-up circuit for relay OJ, over back contact 51 of relay OR and back contact 52 of relay OK. When relay OJ becomes 45 energized, a circuit is completed over back contact 51 of relay OR, contact 54-54^b of relay OK and front contact 55 of relay OJ, to energize relay OB₁. When relay OB₁ picks up, a circuit is completed for relay OK, over back contact 51 of relay OR, contact 54-54^b of relay OK, front contact 55 of relay OJ, front contact 59 of relay OB₁, and front contact 76 of relay OC₁. Relay OK therefore becomes energized, whereupon the pick-up circuit just traced is opened, but relay 55 OK is now stuck up over back contact 51 of relay OR and its own front contact 54-54^a. When relay OK becomes energized, the circuit previously traced for relay OJ is also interrupted but relay OJ, having a release time of 12 cycles, does 60 not immediately release. When relay OK closes its front contact 53, a stick circuit is completed for relay OB₁, over back contact 51 of relay OR, front contact 53 of relay OK, and front contact 59 of relay OB₁. The energization of relay OK also 65 closes a stick circuit for relay OC₁, over front contact 56 of relay OK, back contact 70 of relay OC_{1a}, and front contact 60 of relay OC₁. When relay OC₁ picked up, it completed a circuit for 70 relay OJP over back contact 51 of relay OR, back contact 53 of relay OK, front contact 60 of relay OC₁, back contact 69 of relay OC_{1a}, and front contact 57 of relay OJ, and relay OJP picked up at the same time as relay OB₁. When relay OJP 75

picked up, its front contact 58 connected relay OK_a in parallel with relay OJP, and relay OK_a therefor picked up at the same time as relay OK. After relay OK has closed its front contact, 5 battery is supplied to relays OJP and OK_a over front contact 57 of relay OJ and front contact 56 of relay OK to hold the latter relays energized until OK releases.

The operation of relays OJP and OK_a just described has no particular significance in relation to the operation of the chains of counting relays now being described and is only mentioned in passing. Under some conditions, the first impulse of the code may be prolonged so that relay 15 OJ becomes de-energized but this operation also is unrelated to the operation of the counting relays and further reference will be had to it as the description proceeds.

At the end of the first impulse, relay OR again becomes energized, thereby opening back contact 51 and closing front contact 51. The stick circuit for relay OK is now open at back contact 51 of relay OR but relay OK is sufficiently slow-acting to bridge the comparatively brief intervals 25 of energization of relay OR which never exceeded 8 cycles, so that relay OK remains closed until the code has been completed. When relay OR becomes energized, a circuit is completed for relay OJ over front contact 51 of relay OR, and front contact 52 of relay OK, and it will therefore be seen that relay OJ is energized during each interval between successive impulses in a code supplied to the line circuit. The energization of relay OR interrupted the stick circuit for 35 relay OB₁, but has no effect upon relay OC₁ which is now held up over front contact 56 of relay OK, back contact 70 of relay OC_{1a}, and front contact 60 of relay OC₁. Relay OB₁ is therefore de-energized, but before this relay opens 40 its front contacts, a pick-up circuit is completed for relay OB_{1a}, over front contact 51 of relay OR, front contact 61 of relay OK and front contact 62 of relay OB₁. Relay OB_{1a} therefore becomes energized and is subsequently stuck up over front contact 51 of relay OR, front contact 61 of relay OK, and front contact 63 of relay OB_{1a}. After the expiration of its brief holding 45 interval, relay OB₁ releases.

When relay OR becomes de-energized at the beginning of the second impulse in a code, current is again supplied to relay OK, and the holding circuit for relay OJ opens. Relay OJ remains energized, however, unless the second impulse is prolonged. The de-energization of relay OR also completes a pick-up circuit for relay OB₂ over back contact 51 of relay OR, front contact 53 of relay OK, back contact 59 of relay OB₁, and front contact 64 of relay OB_{1a}. The stick circuit for relay OB_{1a} is now open at front contact 51 of relay OR and relay OB_{1a} becomes de-energized. Relay OB₂ is now held up, however, by virtue of its stick circuit over back contact 51 of relay OR, front contact 53 of relay OK, and front contact 65 of relay OB₂.

The operation of the remaining relays "B" in the counting chain is similar to that just described for relays OB₁, OB_{1a} and OB₂, it being noticed that each energization and de-energization of relay OR picks up a succeeding relay B in the chain and de-energizes the preceding relay. It should also be noted that the pick-up circuit for each counting relay includes a front contact of the preceding relay in the chain and a back contact of the second preceding relay in the chain so that operation of the counting chain is im-

possible unless the relays operate successively and in order.

The operation of the relays continues until relay OR becomes energized at the expiration of the fourth impulse of the code. When this happens, the stick circuit for relay OB₄, now energized, is interrupted, but before relay OB₄ releases, a pick-up circuit is closed for relay OC_{1a}, over front contact 51 of relay OR, front contact 61 of relay OK, back contact 66 of relay OB_{3a}, front contact 67 of relay OB₄, and front contact 68 of relay OC₁. Relay OC_{1a} therefore becomes energized and after relay OB₄ releases, relay OC_{1a} is held up over a stick circuit including front contact 51 of relay OR, front contact 61 of relay OK, and front contact 69 of relay OC_{1a}. When relay OR next becomes de-energized, at the beginning of the fifth impulse, relay OB₁ becomes energized over back contact 51 of relay OR, front contact 53 of relay OK, back contact 299 of relay OB₄, and front contact 71 of relay OC_{1a}. Furthermore, when relay OC_{1a} became energized, the stick circuit for relay OC₁ was opened at back contact 70 of relay OC_{1a} so that relay OC₁ released and closed its back contact 60 to complete a pick-up circuit for relay OC₂ over front contact 56 of relay OK, back contact 60 of relay OC₁, and front contact 70 of relay OC_{1a}. Relay OC₂ therefore picks up and closes its stick circuit over front contact 56 of relay OK, back contact 72 of relay OC_{2a} and front contact 71 of relay OC₂. During the fifth impulse, then, relay OC₂ is energized and relay OB₁ is energized. Relay OC₂ remains energized as the relays of the "B" chain are successively energized by the fifth, sixth, seventh and eighth impulses in the same manner as described in connection with the successive operation of these relays in response to the first four impulses of a code. In similar manner, the ninth impulse commences 40 the successive operation of the counting relays of the "B" chain for the third time, and during the energization of these relays in response to the ninth, tenth, eleventh and twelfth impulses, relay OC₃ is energized. The thirteenth impulse 45 of a code, picks up relays OB₁ and OC₄ and if the code contains sixteen impulses, the fourteenth, fifteenth and sixteenth impulses energize relays OB₂, OB₃ and OB₄ in succession, while relay OC₄ remains energized. The final 50 impulse of every code is prolonged and during this prolonged impulse, relays OJ, OJP and OK_a become de-energized in succession. When relay OR becomes energized after this final impulse, however, relays OJ, OJP and OK_a again become 55 energized in succession. Relay OR now remains steadily energized, so that relay OK is de-energized. At the expiration of the holding time of approximately 12 cycles, relay OK releases. The opening of the front contacts of relay K de- 60 energizes relays OJ, OJP, OK_a and any of the counting relays "B" or "C" which may happen to be energized. The apparatus is therefore restored to its normal condition.

It should be pointed out that relay OJ is energized during the intervals between successive impulses of a code, but is de-energized during each impulse. If any impulse exceeds the holding time of relay OJ of approximately 12 cycles, 70 therefore, this relay becomes de-energized, and if the impulse continues for 8 cycles more, relay OJP also releases. Relays OJ and OJP remain energized during the short impulses of a code but release in succession during each prolonged 75

impulse. The functions of these relays will be described hereinafter.

It should also be pointed out that if relay OR becomes energized during the reception of a code for a longer time than the release time of relay OK, this relay will release, thereby breaking the stick circuit for any counting relay which may happen to be energized and also releasing relays OJ, OJP and OKa. This operation restores 10 the counting chains to their original condition and prevents operation of any function due to an incorrect code or an accidental interruption in the line circuit.

The operation of the counting relays at each 15 station in response to operation of the associated line relay is similar to the operation just described in connection with the despatcher's office with the single exception that the station equipment does not include the repeater relay OJP, 20 but relay Ka at each station is controlled directly over a front contact of the corresponding relay J. In all other respects the station equipment is identical with the office equipment and the 25 operation will be understood without tracing it in detail.

In addition to the apparatus previously described, the despatcher's office is provided with three lock-out relays OL1, OL2, and OL3 and with three group selector relays OG1, OG2 and 30 OG3. Furthermore, the office is provided with a station relay and a starting relay for each panel. Each station relay is designated by the reference character OS and each starting relay by the reference character OH, with suffixes corresponding 35 to the panel with which such relay is identified. The office equipment also includes a series of register or indication storing relays OF1 to OF7, inclusive, and a delivery relay OF8, while the apparatus of each office panel includes a 40 series of indication relays ONWI, ORWI, ORT1, ORA1, OLH1, and ORH1.

In explaining the operation of the apparatus, I will assume that all parts occupy the positions in which they are shown in the drawings, that is, 45 all sections of track at station No. 1 are unoccupied, so that all approach and track relays are energized, repeater relay ITP is energized, switch 3 occupies its normal position and signal ILA is cleared to permit westbound moves over 50 the switch 3. At the despatcher's office, the apparatus associated with panel No. 1 corresponds in condition with the devices at station No. 1. The indication relay ONWI is energized by virtue of a stick circuit which may be traced 55 from terminal B, over back contact 78-78^b of station relay OS1 (now de-energized) back contact 79 of starting relay OH1 (now de-energized) and front contact 80 of relay ONWI. Relay OLH1 is also energized, its stick circuit passing 60 from terminal B, through back contact 78-78^b of relay OS1, front contact 81 of relay OLH1, and winding of relay OLH1 to terminal C.

The indication lamps on the several panels are supplied with energy in any suitable manner. 65 As here shown, these lamps are at times supplied with alternating current from busses 82 and 83 which are connected with the secondary of transformer t when the "power-off" relay w is energized. The relay w is connected across the secondary of transformer t, the primary of which is constantly supplied with alternating current not shown in the drawings. Under ordinary conditions, therefore, the buses 82 and 83 receive alternating current for the control of the panel 70 lamps, but if for any reason the supply of alter-

nating current should fail, relay w would become de-energized and the busses 82 and 83 would then be connected with terminals B¹ and C¹ of an auxiliary source of energy. Circuits for the track indication lamp 87 of panel No. 1 and track indication lamp 86 of the approach panel are open so that these lamps are de-energized. The switch normal indication lamp 88 is connected with busses 82 and 83 over front contact 84 of relay ONWI, so that this lamp is lighted to indicate 10 that the switch 3 at station No. 1 occupies its normal position in accordance with the position of the switch control lever 1p on panel No. 1. In similar manner, the left-hand signal clear indication lamp 90 is connected with busses 82 15 and 83 over front contact 85 of relay OLH1 so that this lamp is lighted to indicate that a west-bound signal at station No. 1 is clear in accordance with the position of the signal control lever 1q. Since the operator knows that the switch 20 occupies its normal position, he can infer that the signal which is clear is ILA which governs traffic over the switch in its normal position. All other lamps on panel No. 1 are extinguished. Furthermore, all other relays at the despatcher's 25 office are de-energized with the exception of relay OR which is, of course, energized because it is included in the normally closed line circuit.

I will now assume that the operator wishes to reverse switch 3 at station No. 1 and also to clear 30 signal ILB to authorize traffic movements from section b-f into siding r. In order to accomplish this result, the operator reverses the switch control lever 1p and reverses the signal control lever 1q and operates the starting button OP1. The 35 closing of the starting button OP1 connects starting relay OH1 of panel No. 1 with terminal B so that this relay becomes energized. Relay OH1 is held energized, after the starting button is released, over a stick circuit including its own front 40 contact 123 and back contacts 122 and 122b of the corresponding station relay OS1. It will be noted that back contact 79 of relay OH1 is included in the stick circuit for relay ONWI and since the starting relay OH1 is now energized, 45 relay ONWI releases, thereby opening the circuit for lamp 88 at front contact 84 of relay ONWI, and extinguishing this lamp. The lamp 90 however, remains lighted. Relay OH1 controls a circuit for the master relay OM at the 50 despatcher's office which circuit may be traced from terminal B, over front contact 93 of relay OH1, back contact 94 of relay OB2, back contact 95 of relay OK, back contact 96 of relay OKa, and winding of relay OM to terminal C. It 55 should be noted that this circuit is closed only if relays OK and OKa are both de-energized. It will be remembered, however, that relays OK and OKa are energized when a code is being transmitted over the line circuit so that relay OM can 60 become energized over the circuit just traced only if the line circuit is free for use. When relay OM becomes energized a circuit is completed for relay OT which may be traced from terminal B, over back contact 97 of relay OB1, back contact 65 98 of relay OB2, back contact 99 of relay OB3, back contact 100 of relay OB4, front contact 101 of relay OM, and winding of relay OT to terminal C. Relay OT therefore becomes energized and 70 interrupts the line circuit at back contact 102 of relay OT. This operation of relay OT starts the first impulse of a control code and of course de-energizes the line relay OR at the despatcher's office and also de-energizes all relays R at the 75 several remote stations. The de-energization of

relay OR sets the counting chains B and C into operation in the manner previously described, that is to say, relays OJ, OC1, OB1, OK, OJP and OKa become energized. When relay OK becomes energized over a circuit which may be traced from terminal B, over front contact 56 of relay OK, front contact 103 of relay OB1, front contact 104 of relay OC1, and winding of relay OL1 to terminal C. Relay OL1 is subsequently stuck up over a circuit which may be traced from terminal B, over front contact 56 of relay OK, front contact 105 of relay OKa, back contact 106 of relay OC4, back contact 107 of relay OL3, back contact 108 of relay OL2, front contact 109 of relay OL1 and winding of relay OL1 to terminal C. Relay OL1 is therefore picked up and stuck up during the first impulse of the control code.

When relay OK became energized the pick-up circuit previously traced for relay OM was opened at back contact 95 of relay OK but relay OM is now held in its energized condition over a stick circuit which was closed when relay OKa became energized and which may be traced from terminal B, over front contact 56 of relay OK, front contact 110 of relay OM, front contact 96 of relay OKa and winding of relay OM to terminal C. The circuit previously traced for relay OT over back contacts of the counting relays OB1, OB2, etc., was interrupted at back contact 97 of relay OB1 when the latter relay became energized, but a holding circuit was completed for relay OT when relay OJP became energized and this circuit passes from terminal B, over front contact 97 of relay OB1, front contact 111 of relay OC1, front contact 112 of relay OJP, front contact 113 of relay OT, front contact 101 of relay OM, and winding of relay OT to terminal C. It should also be noticed that when relay OK became energized the circuit was interrupted for relay OJ, and when relay OJ releases, the circuit for relay OJP is interrupted. When relay OJP releases, the stick circuit just traced for relay OT is interrupted at front contact 112 of relay OJP, and relay OT is then de-energized to close the line circuit and terminate the first impulse. It will be clear from the foregoing that during the first impulse, the line circuit was held open for a time interval equal to the sum of the release times of relays OJ, OJP and OT.

When relay OT becomes de-energized at the conclusion of the first impulse, relay OR becomes energized and picks up relay OB1a as previously described. Relay OB1 is also de-energized, and when this relay closes its back contact 97 the circuit is again completed to pick up relay OT and initiate the second impulse. The energization of relay OT opens the line circuit, thus causing relay OR to become de-energized. Relay OB2 is then energized and is subsequently stuck up over its own front contact as explained hereinbefore. When relay OB2 picks up it opens the normal circuit for relay OT at back contact 98 of relay OB2, but a holding circuit for relay OT is now closed from terminal B, over front contact 93 of relay OH1, front contact 94 of relay OB2, front contact 114 of relay OL1, front contact 113 of relay OT, front contact 101 of relay OM, and winding of relay OT to terminal C. Relay OT therefore remains energized, until relay OL1 releases, to prolong the second impulse. This prolonged impulse allows relays OJ and OJP to release in succession and when relay OJP releases, a pick-up circuit is completed for one of the group selector relays and energizes relay OG1

over a circuit which passes from terminal B, over front contact 56 of relay OK, front contact 115 of relay OKa, back contact 116 of relay OJ, back contact 117 of relay OJP, front contact 118 of relay OB2, front contact 119 of relay OL1, front contact 120 of relay OC1 and winding of relay OG1 to terminal C. Relay OG1 therefore becomes energized and when this occurs, current flows over the circuit just traced as far as front contact 120 of relay OC1 and thence over front contact 121 of relay OG1, and winding of relay OL2 to terminal C. Relays OG1 and OL2 therefore pick up in succession. The energization of relay OL2 opens the stick circuit for relay OL1, which thereupon becomes de-energized. Relay OL2 remains energized by virtue of a stick circuit which passes from terminal B, over front contact 56 of relay OK, front contact 105 of relay OKa, back contact 106 of relay OC4, back contact 107 of relay OL3, front contact 108 of relay OL2, and winding of relay OL2 to terminal C. Current also flows over the stick circuit just traced as far as front contact 108 of relay OL2 and thence through front contact 121 of relay OG1 and winding of relay OG1 to terminal C. Relays OL2 and OG1 are therefore held in their energized condition. When relay OL1 releases, the holding circuit for relay OT is interrupted at front contact 114 of relay OL1, and relay OT becomes deenergized to terminate the second impulse.

When back contact 102 of relay OT closes, the line circuit is again completed and relay OR becomes energized. When front contact 51 of relay OR closes, relay OB2a becomes energized and is subsequently stuck up over its own front contact. Relay OB2 is now de-energized and when this relay releases, the closing of its back contact 98 completes the pick-up circuit for relay OT to start the third impulse.

It should be observed that when relay OR became energized, relays OJ and OJP were again energized over front contacts of relay OK and a front contact of relay OR. At the beginning of the third impulse caused by energization of relay OT, relay OR again becomes de-energized and picks up relay OB3. Relay OB2a, of course, becomes de-energized and releases. The energization of relay OB3 interrupts the pick-up circuit for relay OT, and since there is no holding circuit now closed for relay OT, this relay again releases and terminates the third impulse which is therefore short.

The releasing of relay OT again picks up relay OR, and when this occurs relay OB3a picks up and sticks over its own front contact. Relay OB3 then releases and closes the pick-up circuit for relay OT at back contact 99 of relay OB3. As a result, relay OT again becomes energized and interrupts the line circuit and de-energizes relay OR to start the fourth impulse. When relay OR becomes de-energized at the beginning of the fourth impulse, relay OB4 becomes energized and is subsequently stuck up over its own front contact. Relay OB3a then releases. The energization of relay OB4 interrupts the pick-up circuit for relay OT at back contact 100 of relay OB4, and since no holding circuit is now completed for relay OT, that relay releases, and when its back contact 102 closes, the line circuit is again closed to pick up relay OR and terminate the fourth impulse.

The energization of relay OR closes the pick-up circuit for relay OC1a over front contacts 67 and 68 of relays OB4 and OC1 relay OC1a be-

comes energized. The opening of back contact 70 of relay OC1a interrupts the stick circuit for relay OC1, which latter relay now releases. When relay OC1 closes its back contact 60, relay 5 OC2 becomes energized as described hereinbefore, and is subsequently stuck up over its own front contact 71 and back contact 72 of relay OC2a. When relay OB4 becomes de-energized following the energization of relay OR, the pick-up circuit 10 for relay OT is again closed and this relay becomes energized to open the line circuit to start the fifth impulse.

When relay OR becomes de-energized, the closing of back contact 51 picks up relay OB1, which 15 subsequently sticks up over its front contact 59. This operation of relay OB1 interrupts the pick-up circuit for relay OT, but relay OT is now held up over a circuit which may be traced from terminal B over front contact 290 of relay OG1, front 20 contact 124 of relay OH1, front contact 125 of relay OB1, front contact 126 of relay OC2, front contact 113 of relay OT, front contact 101 of relay OM, and winding of relay OT to terminal C. Relay OT is therefore held energized until relay 25 OG1 becomes deenergized, thereby prolonging the fifth impulse. This long impulse will allow relays OJ and OJP to release sucessively, and when this occurs a pick-up circuit is completed for relay OS1 from terminal B, over front contact 56 of 30 relay OK, front contact 115 of relay OKa, back contact 116 of relay OJ, back contact 117 of relay OJP, front contact 127 of relay OB1, front contact 128 of relay OC2, front contact 129 of relay OG1, and winding of relay OS1 to terminal C. 35 When relay OS1 becomes energized, current flows over its pick-up circuit just traced as far as front contact 129 of relay OG1, and thence over front contact 130 of relay OS1, back contact 131 of relay OF8 (now closed) and winding of relay OL3 to terminal C. Relay OL3 therefore becomes energized and breaks the stick circuits for relays OL2 and OG1. Relay OL3 is now stuck up over a circuit which may be traced from terminal B, over front contact 56 of relay OK, front contact 40 105 of relay OKa, back contact 106 of relay OC4, front contact 107 of relay OL3, back contact 131 of relay OF8 and winding of relay OL3 to terminal C. A stick circuit is also completed for relay OS1 which is the same as the stick circuit just traced for relay OL3 as far as front contact 107 of relay 45 OL3, passing thence over front contact 130 of relay OS1, and winding of relay OS1 to terminal C. The release of relay OG1 interrupted the holding circuit for relay OT, and relay OT now releases to terminate the fifth impulse which has 50 been prolonged as just described.

It should be noted that when relay OG1 releases, it interrupts the holding circuits controlled by relays OH2, OH3 and OH4, thereby 55 making it impossible for starting relays associated with other panels to interfere with the control of the code now being delivered which originated at panel No. 1. Furthermore, the de-energization of relay OG1 interrupts the pick-up circuits for relays OS2, OS3 and OS4 so that no additional station selector relays at the despatcher's office may be energized. Relays OG1 and OL2 are, of course, now de-energized. It should also be pointed out that when relay OS1 became energized, the stick circuit for relay OH1 was opened, so that relay OH1 now releases. Furthermore, the operation of relay OS1 interrupts the stick circuit previously traced for relay OLH1 over back contact 78-78b of relay OS1. A holding circuit 60 is now completed, however, for relay OLH1 from

terminal B, over front contact 132 of relay OM, front contact 78-78a of relay OS1, and front contact 81 of relay OLH1, and winding of relay OLH1 to terminal C. Relay OLH1 therefore remains energized and lamp 90 on panel No. 1 remains lighted. 5

When relay OT becomes de-energized, following the opening of relay OG1 and closing of its back contact 102, restores the line circuit, so that relay OR becomes energized, to terminate 10 the fifth impulse. The energization of relay OR picks up relay OB1a, and then relay OB1 releases to close its back contacts and energize relay OT to start the sixth impulse. This operation of relay OT de-energizes relay OR which 15 picks up relay OB2 to open the circuit for relay OT and relay OB1a, of course, releases. The opening of the pick-up circuit for relay OT at back contact 98 of relay OB2 releases relay OT, because no holding circuit is now completed for 20 this relay. When relay OT closes its back contact 102, the line circuit is again closed to terminate the sixth impulse and pick up relay OR. This operation of relay OR energizes relay OB2a and releases relay OB2. When back contact 25 98 of relay OB2 becomes closed the pick-up circuit is completed for relay OT and that relay becomes energized to open the line circuit and start the seventh impulse. When relay OR becomes deenergized at the beginning of the seventh 30 impulse, relay OB3 becomes energized and relay OB2a releases. The energization of relay OB3 interrupts the pick-up circuit for relay OT, and since there is now no holding circuit for this relay, relay OT releases to close the line circuit 35 and terminate the seventh impulse. Relay OR therefore becomes energized and picks up relay OB3a and releases relay OB3. When back contact 99 of relay OB3 closes, the pick-up circuit is completed for relay OT and this relay opens 40 its back contact 102 to interrupt the line circuit and start the eighth impulse. When relay OR becomes de-energized, relay OB4 picks up and relay OB3a releases. The energization of relay 45 OB4 interrupts the pick-up circuit for relay OT and since no holding circuit is completed for this relay it closes its back contact and restores the line circuit to terminate the eighth impulse. The closing of line relay OR picks up relay OC2a, and the latter relay opens its back contact 72 in the 50 stick circuit for relay OC2, thereby releasing relay OC2. When relay OC2 closes its back contact 71, relay OC3 becomes energized over its pickup circuit including contact 56 of relay OK, back contact 71 of relay OC2 and front contact 72 of relay OC2a, and relay OC3 is then held energized over its stick circuit including its own front contact 73 and back contact 74 of relay OC3a. Relay 55 OB4 then releases, and when back contact 100 of relay OB4 becomes closed the pick-up circuit is completed for relay OT to energize this relay and open the line circuit to start the ninth impulse. Relay OR then becomes de-energized and picks up relay OB1, thereby interrupting the circuit for relay OT at back contact 97 of relay OB1, 60 and releasing relay OC2a. Relay OT then releases and restores the line circuit to terminate the ninth impulse. When relay OR becomes energized, relay OB1a picks up and relay OB1 becomes de-energized, thereby again restoring the 65 pick-up circuit for relay OT and breaking the line circuit to start the tenth impulse. When relay OR becomes de-energized, relay OB2 is picked up and relay OB1a releases. The energization of relay OB2 interrupts the pick-up circuit 70 75

for relay OT at back contact 98 of relay OB2 but relay OT is now held energized over a circuit which may be traced from terminal B, over back contact 97 of relay OB1, front contact 98 of relay 5 OB2, switch control lever 1p on panel No. 1 in its reverse or right-hand position, front contact 295 of relay OS1, front contact 133 of relay OC3, front contact 112 of relay OJP, front contact 113 of relay OT, front contact 101 of relay OM, and 10 winding of relay OT to terminal C. Relay OT is held energized by the circuit just traced to prolong the tenth impulse. During this long impulse, relays OJ and OJP release successively and when relay OJP releases, the opening of front 15 contact 112 of relay OJP interrupts the holding circuit for relay OT and permits that relay to release and restore the line circuit to terminate the tenth impulse. The relay OR then becomes energized, picking up relays OJ and OJP and 20 also relay OB2a. Relay OB2 then releases and restores the normal pick-up circuit for relay OT to open the line circuit and start the eleventh impulse. Relay OR then becomes de-energized, picking up relay OB3 and releasing relay OB3a. 25 The energization of relay OB3 breaks the pick-up circuit for relay OT and since there is no holding circuit for relay OT, under these conditions, relay OT releases to terminate the eleventh impulse. The relay OR then picks up, 30 energizing relay OB3a, and releases relay OB3, closing the pick-up circuit for relay OT. When the latter relay becomes energized, the line circuit is opened to start the twelfth impulse. When relay OR becomes de-energized, relay OB4 35 picks up and relay OB3a releases. The energization of relay OB4 opens the pick-up circuit for relay OT, but this relay is now held energized over a circuit from terminal B, through back contact 97 of relay OB1, back contact 98 of 40 relay OB2, back contact 99 of relay OB3, front contact 100 of relay OB4, signal control lever 1q on panel No. 1 in its reverse or right-hand position, front contact 134 of relay OS1, front contact 133 of relay OC3, front contact 112 of relay 45 OJP, front contact 113 of relay OT, front contact 101 of relay OM and winding of relay OT to terminal C. Relay OT therefore holds the line circuit open to prolong the twelfth impulse. During this long impulse, relays OJ and OJP release 50 successively and when relay OJP opens its front contact 112, the holding circuit for relay OT is interrupted. When relay OT closes its back contact 102, the line circuit is restored to terminate the twelfth impulse. Relay OR therefore picks 55 up and relay OC3a becomes energized and opens its back contact 14 to release relay OC3. When relay OC3 releases, the pickup circuit for relay OC4 is closed over front contact 56 of relay OK, back contact 73 of relay OC3 and front contact 60 74 of relay OC3a so that relay OC4 becomes energized. Relay OC4 is then held energized over its stick circuit including its own front contact 75 and front contact 56 of relay OK until relay OK releases at the end of the code. Relay OB4 then releases and when back contact 100 of this 65 relay becomes closed, a pick-up circuit is again completed for relay OT to start the thirteenth impulse. Relays OJ and OJP became energized when relay OR picked up. At the start of the 70 thirteenth impulse, relay OR becomes deenergized, thereby picking up relay OB1 and releasing relay OC3a. The thirteenth impulse is the final or delivery impulse of the control code and this impulse is longer than any other impulse in 75 the control code. The pick-up circuit for relay OT is, of course, interrupted as soon as relay OB1 picks up but a holding circuit for relay OT is now closed from terminal B, over front contact 97 of relay OB1, front contact 135 of relay OC4, front contact 113 of relay OT, front contact 101 of relay OM, and winding of relay OT to terminal C. It should be noted that when relay OC4 becomes energized it breaks the stick circuits for relays OL3 and OS1 at back contact 106 of relay OC4. During this thirteenth impulse, relay OJ 10 becomes de-energized and when this relay releases, relay OJP becomes de-energized. When relay OJP releases, it opens the circuit for relay OKa, which then releases and interrupts the holding circuit for relay OM. When relay OM 15 releases, it opens the holding circuit for relay OT and allows relay OT to close its back contact 102 and restore the line circuit to terminate the thirteenth impulse. When relay OR becomes energized, relays OJ, OJP and OKa again become 20 energized, relay OB1a also picks up and relay OB1 releases. Relay OM does not become energized, however, and the release of relay OB1 does not pick up relay OT, because the pick-up circuit for relay OT is now open at front contact 101 of 25 relay OM. The line circuit, therefore, remains closed, relay OR remains steadily energized and after a brief interval, relay OK releases. When relay OK releases, it de-energizes relays OJ, OJP, OKa, OB1a and OC4. It should be noted that as 30 soon as relays OK and OKa have released successively, the pick-up circuit for relay OM is again prepared so that the operation of a push button on one of the control panels will immediately start the transmission of another control 35 code. If no push button is operated, however, it will be apparent, that all of the relays remain de-energized except relay OR and relay OLH1. With reference to the latter relay, it will be observed that the stick circuit for the relay was 40 restored to the back contact 78—78b of relay OS1 at the conclusion of the control code. After the control code has been transmitted to the line circuit, then, and before the reception of a corresponding indication code, lamp 90 on panel No. 45 1 continues to burn but all other lamps are extinguished.

It will be observed that relay OH1 is provided with an auxiliary stick circuit including its own front contact 123, front contact 122—122a of relay 50 OS1, and back contact 132 of relay M. The purpose of this auxiliary stick circuit is to maintain relay OH1 energized after operation of push button OP1, while an indication code is being received at panel No. 1. As will be explained in detail hereinafter, relay OS1 is energized under these conditions, but the stick circuit just traced holds relay OH1 energized so that the apparatus remains in condition to transmit a control code after the indication code is completed. 55

In the foregoing explanation, I have described the operation of the apparatus at the despatcher's office in transmitting a control code to the line circuit, and it will be seen that this control code consists of thirteen impulses, the first, second, 60 fifth, tenth, twelfth and thirteenth of which are long, while the remaining are short impulses. The first or locking impulse is prolonged by the successive releases of relays OJ, OJP and OT and is approximately 28 cycles in length. The 65 second and fifth impulses are for the purpose of selecting a definite one of the stations controlled by the despatcher's office, and these two impulses are approximately equal in length. Impulse 2 being determined by the consecutive release of 70 75

relays OJ, OJP, OG1, OL2, OL1 and OT, while impulse 5 is determined by the consecutive releases of relays OJ, OJP, OL3, OL2 and OT. Each of impulses 2 and 5 are substantially 30 cycles long. The tenth and twelfth impulses are function selecting impulses and each is approximately 28 cycles long, being determined by the consecutive releases of relays OJ, OJP and OT. The thirteenth or final impulse of the control code is determined by the consecutive releases of relays OJ, OJP, OKa, OM and OT, this final impulse is substantially 45 cycles long.

I will now describe the operation of the apparatus at station No. 1, in response to the control code thus transmitted over the line circuit. It should be kept in mind that the operation of the apparatus at the remaining stations is similar in all respects to the operation of the apparatus at station No. 1 except that the several stations are selectively responsive to the location in the control code of the second and third long impulses, and only station No. 1 will be responsive to the particular code just described.

In addition to the relays previously described, station No. 1 is provided with a lock-out relay L, a group selector relay IG, a station selector relay IS, and a series of register relays IF1 to IF4 and a delivery relay IF5. Furthermore, the station is provided with a plurality of relays IH, ITD, ITK, IAD, IAK and IHK which are utilized for starting purposes when the apparatus at the station is operating to transmit a code to the line circuit.

As shown in the drawings (Fig. 4) the route stick relay INWS is stuck up over a circuit which may be traced from terminal B, over contact 5 operated by dual selector mechanism of switch 3, normal contact 164 of key release k, back contact 169 of register relay IF5, front contact 186 of relay INWS and contact 30 of thermo-sensitive relay h2 to terminal C. The switch occupies its normal position so that the indication relay IKR is energized. The traffic direction stick relay ILH is also energized, the stick circuit for this relay passing from terminal B, through contact 5 of the dual selector mechanism of switch 3, normal contact 164 of key release k, back contact 174 of relay IF5, back contact 180 of relay IRH, front contact 179 of relay ILH, winding of relay ILH to terminal C. Since relay ILH is energized and relay IKR is energized in the normal direction, relay ILAH is energized and signal ILA is clear. Relay IX is therefore deenergized, this relay being energized as previously explained only when the signals at station No. 1 are all at stop.

The counting relay chains IB1, IB1a, etc., and IC1, IC1a, etc., are controlled in precisely the same manner as the corresponding counting chains discussed in connection with the dispatcher's office and illustrated in Fig. 1. When the first impulse of the control code transmitted from the dispatcher's office is transmitted to the line circuit, the line relay at each station becomes de-energized but these relays subsequently follow the code supplied to the line circuit. When relay IR at station No. 1 first becomes de-energized, relays IJ, IC1, IB1, IKa and IK become energized as will be understood from the drawings without tracing the circuits for these relays in detail. When relay IK picks up, the circuit for relay IJ is interrupted and since the first impulse of a control code is long, relay IJ opens at the expiration of its release period. It will be remembered that the locking impulse of

the control code is approximately 28 cycles long and that the release time of relay IJ at station No. 1 is approximately 16 cycles, and it follows that after relay IJ releases, there is a brief interval of time during which relay IJ is open and before relay IR again becomes energized to pick up relay IJ. During this brief interval, a pick-up circuit is completed for a lock-out relay at each remote station. At station No. 1 this pick-up circuit may be traced from terminal B, over front contact 296 of relay IK, front contact 136 of relay IKa, back contact 137 of relay IJ, front contact 138 of relay IB1, front contact 139 of relay IC1 and winding of relay IL to terminal C. Relay IL therefore becomes energized and is subsequently held in its energized condition until the conclusion of the control code by virtue of a stick circuit which passes from terminal B, over front contact 296 of relay IK, front contact 136 of relay IKa, front contact 140 of relay IL, and winding of relay IL to terminal C. At the end of the first impulse of the control code, relay IR becomes energized, and relay IJ then picks up. Relay IB1a also becomes energized and relay IB1 releases. At the beginning of the second impulse of the code, relay IR becomes de-energized, picking up relay IB2 and releasing relay IB1a. As previously described, the second impulse of the control code is long, and during this long impulse, relay IJ releases. When this happens, a pick-up circuit is completed for group selector relay IG from terminal B, over back contact 141 of relay IB1, front contact 142 of relay IB2, jumper 143, front contact 144 of relay IC1, back contact 145 of relay IJ, front contact 146 of relay IC1, and winding of relay IG to terminal C. Relay IG thereupon becomes energized and is subsequently held in its energized condition until the conclusion of the control code by virtue of a stick circuit which passes from terminal B, over front contact 296 of relay IK, front contact 136 of relay IKa, front contact 147 of relay IG and winding of relay IG to terminal C. Of course, the line relays IR at each of the other stations operate in synchronism with relay IR and this second long impulse of the code picks up the group selector relay corresponding to relay IG at stations 2, 3 and 4, as well as at station No. 1. At the conclusion of the third impulse, relay IR again becomes energized to pick up relay IJ and also relay IB2a. The third impulse causes relay IB3 to become energized and releases relay IB2a. This impulse is short, however, and relay IJ does not release. In similar manner the fourth impulse is short and relay IJ does not release during this impulse. At the beginning of the fifth impulse, however, relays IC2 and IB1 become energized and since this fifth impulse is long, relay IJ releases, whereupon, a pick-up circuit is completed for the station relay S at only one of the stations which have their group selector relays energized. In the present instance the station relay is picked up at station No. 1, the circuit passing from terminal B, over front contact 141 of relay IB1, jumper 148, front contact 149 of relay IC2, back contact 145 of relay IJ, front contact 150 of relay IC2, front contact 151 of relay IG, and winding of relay IS to terminal C. Relay IS is subsequently held up until the conclusion of the control code by virtue of a stick circuit which passes from terminal B, over front contact 296 of relay IK, front contact 136 of relay IKa, front contact 152 of relay IS and winding of relay IS to terminal C.

The sixth, seventh, eighth and ninth impulses

are all short and accomplish nothing at station No. 1, except to step along the counting relay chains so that when the tenth impulse is received, relays 1B2 and 1C3 are energized. This tenth impulse is long and relay 1J therefore releases. When this happens, current flows from terminal B, over front contact 296 of relay 1K, front contact 136 of relay 1Ka, back contact 137 of relay 1J, front contact 153 of relay 1S, front contact 154 of relay 1C3, front contact 155 of relay 1B2, and winding of relay 1F2 to terminal C. Relay 1F2 is subsequently stuck up over a circuit including its own front contact 156 and front contacts 296 and 136 of relays 1K and 1Ka, respectively. At the conclusion of the tenth impulse, the closing of relay 1R again picks up relay 1J. The eleventh impulse is short so that relay 1J does not become de-energized during this impulse. The twelfth impulse is long, however, and during this impulse relay 1J releases while relays 1B4 and 1C3 are energized. A pick-up circuit is then completed for relay 1F4 from terminal B, over front contact 296 of relay 1K, front contact 136 of relay 1Ka, back contact 137 of relay 1J, front contact 153 of relay 1S, front contact 154 of relay 1C3, front contact 157 of relay 1B4, the winding of relay 1F4 to terminal C. Relay 1F4 is subsequently maintained in its energized condition until the conclusion of the control code by a stick circuit which includes its own front contact 158 and front contacts 296 and 136 of relays 1K and 1Ka, respectively. At the end of the twelfth impulse, the energization of relay 1R picks up relay 1J and also of course, picks up relay 1C3a and drops relays 1C3 and 1B4. When relay 1R becomes de-energized at the beginning of the thirteenth impulse, relay 1C4 becomes energized, relay 1C3a releases, and relay 1B1 is energized. The thirteenth impulse is the final or delivery impulse of the control code and during this long impulse, relay 1J becomes de-energized, and current then flows from terminal B, over front contact 296 of relay 1K, front contact 136 of relay 1Ka, back contact 137 of relay 1J, front contact 138 of relay 1B1, front contact 159 of relay 1S, front contact 160 of relay 1C4, front contact 161 of relay 1L, and winding of relay 1F5 to terminal C. Relay 1F5 is subsequently stuck up over its own front contact 163 and front contacts 296 and 136 of relays 1K and 1Ka, respectively.

When relay 1F5 becomes energized, it breaks the stick circuit for switch control relays 1NWS at back contact 169 of relay 1F5. The switch control relay 1NWS is therefore de-energized. The operation of relay 1F5, however, completes a pick-up circuit for relay 1RWS, from terminal B, over contact 5 of the dual selector mechanism of switch 3, normal contact 164 of key release k, front contact 165 of relay 1F5, back contact 166 of relay 1F1, front contact 167 of relay 1F2, front contact 168 of relay 1V, winding of relay 1RWS and contact 30 of thermo-sensitive relay h1 to terminal C. The closing of relay 1F5 also breaks the stick circuit for relay 1LH at back contact 174 of relay 1F5, and relay 1LH releases. A pick-up circuit is now closed, however, for relay 1RH from terminal B, over contact 5 of the dual selector mechanism of switch 3, normal contact 164 of key release k, front contact 174 of relay 1F5, back contact 175 of relay 1F3, front contact 176 of relay 1F4 and winding of relay 1RH to terminal C.

During the thirteenth impulse, relay 1C4 is energized and front contact 162 of this relay is then

connected in parallel with front contact 136 of relay 1Ka. Relays 1F2, 1F4 and 1F5 are therefore held in their energized condition independently of relay 1Ka. At the conclusion of the thirteenth impulse, relay 1R picks up, and relays 1J and 1Ka are then energized consecutively and relay 1B1 picks up and relay 1B1 releases. Since relay 1R remains closed, relay 1K is, of course, de-energized and at the conclusion of its holding interval, relay 1K releases, thereby de-energizing 10 relays 1B1a, 1C4, 1L, 1G, 1S, 1F2, 1F4 and 1F5. With the apparatus in this condition the equipment at station No. 1 is prepared to receive another code. When relay 1K releases, it also de-energizes relay 1J. When relay 1J releases, it 15 de-energizes relay 1Ka, and when relay 1Ka releases, the starting circuit is prepared to start the transmission of an indication code as will be explained hereinafter.

When relay 1RWS picks up it opens the control 20 circuit for the indication relay 1KR, so that the latter relay becomes de-energized, thereby opening the circuit for any signal control relay which may happen to be energized. In the present instance, relay 1LAH becomes de-energized, there- 25 by restoring signal 1LA to the stop position. Since all signals now occupy the stop position, relay 1X becomes energized. The closing of front contact 25 of relay 1X completes the pick-up circuit previously traced for the contactor 1RW, 30 over front contact 28 of relay 1RWS, and the motor m is operated to reverse switch 3 as described hereinbefore. When the switch has attained its full reverse position, contactor 1RW opens, and indication relay 1KR becomes ener- 35 gized in the reverse direction. Since relay 1RH is now energized and relay 1KR is energized in the reverse direction, a circuit is completed for signal control relay 1RBH, so that relay becomes energized and completes the operating circuit 40 for signal 1RB, to clear the signal.

It should be noted that when relay 1F5 became energized, during the final impulse of the control code, relay 1HD became energized over front contact 183 of relay 1F5 so that relay 1HD 45 is now energized, a stick circuit for the relay passing over its own front contact 185 and back contact 184 of relay 1F8.

It should also be observed that when relay 1F5 became de-energized at the conclusion of the 50 final impulse of the control code, stick circuits were completed for relays 1RWS and 1RH, the stick circuit for relay 1RWS passing from terminal B, over contact 5 of the dual selector mechanism of switch 3, front contact 164 of key release 55 k, back contact 165 of relay 1F5, front contact 170 of relay 1RWS, winding of relay 1RWS and contact 30 of thermo-sensitive relay h1 to terminal C. The stick circuit for relay 1RH may be traced from terminal B, over contact 5 operated 60 by dual selector mechanism of switch 3, front contact 164 of key release k, back contact 174 of relay 1F5, back contact 182 of relay 1LH, front contact 181 of relay 1RH and winding of relay 1RH to terminal C. 65

I will next assume that the operator wishes to leave switch 3 at station No. 1 in its reverse position, but wishes to clear eastbound signal 1LB instead of the westbound signal 1RB over this route. In order to accomplish this, he leaves the 70 switch control lever 1p on panel No. 1 at the office in its reverse or right-hand position and moves the signal control lever 1q to its left-hand position. In order to initiate the transmission to the line circuit of a control code corresponding to 75

the positions now occupied by the levers on panel No. 1, he operates the starting button OP1. The equipment at the office operates to deliver a control code to the line circuit in the manner previously described, and the code has the same characteristics as the code described in detail hereinbefore except that the eleventh impulse of the code is long instead of the twelfth impulse. This is accomplished in the following manner.

- 10 At the beginning of the eleventh impulse, relays OB3 and OC3 at the office are energized, and under these conditions a holding circuit is completed for relay OT which passes from terminal B on Fig. 1 of the drawings, through back contact 97 of relay OB1, back contact 99 of relay OB2, front contact 99 of relay OB3, signal control lever 1q on panel No. 1 in its left-hand position, front contact 134 of relay OS1, front contact 133 of relay OC3, front contact 112 of relay OJP, front contact 113 of relay OT, front contact 101 of relay OM, and winding of relay OT to terminal C. The circuit just traced holds relay OT energized after relay OB3 picks up to break the pick-up circuit for relay OT until relays OJ and OJP release consecutively. When front contact 112 of relay OJP opens, the holding circuit just traced is interrupted and the relay OT becomes de-energized to restore the line circuit and terminate the eleventh impulse. During the twelfth impulse no holding circuit is completed for relay OT, so this impulse is short. In all other respects, the operation of the apparatus at the dispatcher's office is the same as previously described and the code signal then supplied to the line circuit contains 13 impulses of which the first, second, fifth, tenth, eleventh, and thirteenth are long and the remaining impulses are short.

Referring now to the apparatus at station No. 1, when the code last described is received at the 40 station, the operation of the equipment is the same as described hereinbefore except that during the eleventh impulse, relay 1F3 is energized in the following manner:

At the beginning of the eleventh impulse, relays 1B3 and 1C3 are both energized, and since this impulse is long, relay 1J becomes de-energized and a circuit is completed from terminal B, over front contact 296 of relay 1K, front contact 133 of relay 1Ka, back contact 137 of relay 1J, front contact 153 of relay 1S, front contact 154 of relay 1C3, front contact 297 of relay 1B3, and winding of relay 1F3 to terminal C. Relay 1F3 is subsequently held in its energized condition by virtue of a stick circuit including its own front contact 187 and front contacts 296 and 136 of relays 1K and 1Ka. Since the twelfth impulse of the control code now supplied to the line circuit is short, relay 1F4 does not become energized.

- 60 Under the conditions just described, when the final or delivery impulse of the control code is received, and relay 1F5 becomes energized, current is supplied from terminal B, over contact 5 operated by the dual selector mechanism of switch 3, front contact 164 of key release k, front contact 174 of relay 1F5, back contact 171 of relay 1F4, front contact 178 of relay 1F3, and winding of relay 1LH to terminal C. Relay 1LH therefore becomes energized and the opening of back contact 174 of relay 1F5 opens the stick circuit for relay 1RH and allows the latter relay to release. When relay 1F5 again becomes de-energized a stick circuit is completed for relay 1LH including its own front contact 179,

back contact 180 of relay 1RH and back contact 174 of relay 1F5.

It should also be observed that when the control code was received, the stick circuit for relay 1RWS, which is now assumed to be energized was interrupted by the opening of back contact 165 of relay 1F5. When relay 1F5 operated, however, relay 1F2 was energized and the pick-up circuit for relay 1RWS was closed through back contact 166 of relay 1F1 and front contact 167 of relay 1F2, so that when relay 1F5 again becomes de-energized, the stick circuit for relay 1RWS continues to energize this relay and no change is made in the control of the switch 3. When relay 1RH became de-energized, the circuit for relay 1RBS was opened so that signal 1RB was restored to the stop position. Since relay 1LH is now energized and since relay 1KR is energized in the reverse direction, relay 1LBH now picks up, thereby completing the operating circuit for clearing signal 1LB to permit the passage of westbound traffic over switch 3 in its reverse direction.

I will next assume that the operator wishes to restore the switch 3 at station No. 1 to its normal position, and to clear the signal for westbound traffic over the switch in its new position. In order to accomplish this result, he leaves the signal control lever 1q on panel No. 1 in its left-hand position and moves the switch control lever 1p to its normal or left-hand position. He then operates the starting button OP1, whereupon, the apparatus at the office transmits to the line circuit a control code similar to the control codes previously described and having its first, second, fifth, ninth, eleventh and thirteenth impulses long and the remaining impulses short. The operation of the equipment at the office for prolonging the eleventh impulse has already been described and I will now describe the holding circuit for prolonging the ninth impulse to accomplish the restoration of the switch 3 at station No. 1 to its normal position. At the beginning of the ninth impulse, relays OB1 and OC3 at the office are energized, relay OT having been energized by its normal pick-up circuit over back contacts of the counting relays OB1, OB2, etc. This pick-up circuit was opened when relay OB1 became energized, but a holding circuit is now completed for relay OT from terminal B, through front contact 97 of relay OB1, switch control lever 1p in its normal or left-hand position, front contact 295 of relay OS1, front contact 133 of relay OC3, front contact 112 of relay OJP, front contact 113 of relay OT, front contact 101 of relay OM and winding of relay OT to terminal C. Relay OT is therefore held energized to prolong the ninth impulse, until relays OJ and OJP release consecutively. When relay OJP opens its front contact 112, the holding circuit for relay OT is interrupted and that relay releases to restore the line circuit and to terminate the ninth impulse. During the tenth impulse, no holding circuit is completed for relay OT, so that impulse is short.

Referring now to the equipment at station No. 1, when the control code, having its first, second, fifth, ninth, eleventh and thirteenth impulses prolonged, is received at station No. 1, the operation of the apparatus is similar to that previously described except that relays 1F1, 1F3 and 1F5 are energized by the last three long impulses. The operating circuits of relays 1F3 and 1F5 have been described hereinbefore, and the pick-up circuit for relay 1F1 passes from terminal B, through front contact 75

296 of relay IK , from contact 136 of relay IK_a , back contact 137 of relay IJ , front contact 138 of relay IB_1 , front contact 159 of relay IS , front contact 188 of relay IC_3 and winding of relay IF_1 to terminal C. Relay IF_1 is energized over the circuit just traced following the de-energization of relay IJ during the long ninth impulse of the control code and is subsequently stuck up over its own front contact 189 and front contacts of relays IK and IK_a . It is assumed that previous to the reception of the control code just described, relay $IRWS$ was energized. When relay IF_5 becomes energized at the conclusion of the code, the stick circuit for relay $IRWS$ is interrupted, and that relay releases. At the same time, the closing of front contact 169 of relay IF_5 completes a circuit from terminal B, through contact 5 operated by dual selector mechanism of switch 3, contact 164 of key release k , front contact 169 of relay IF_5 , back contact 171 of relay IF_2 , front contact 172 of relay IF_1 , front contact 173 of relay IV , winding of relay $INWS$ and contact 30 of thermo-sensitive relay h_2 to terminal C. Relay $INWS$ therefore becomes energized, and when relay IF_5 again becomes de-energized a stick circuit is completed for relay $INWS$ over its own front contact 186 and back contact 169 of relay IF_5 . The opening of relay $IRWS$ de-energizes the indication relay IK_R , thereby de-energizing any signal control relay and placing all signals at stop. With the signals all in stop position, relay IX is energized and current then flows over front contact 35 of relay $INWS$ to pick up contactor INW . Motor m is then operated, as previously described, to restore switch 3 to its normal position, whereupon the contactor INW is de-energized and the indication relay IK_R becomes energized in its normal direction.

40 When relay IF_5 became energized during the final impulse of the control code, the stick circuit for relay ILH was interrupted, but the pick-up circuit was completed for relay ILH during the time interval that relay IF_5 was energized, so that when relay IF_5 again closes its back contact, relay ILH is held in its energized condition. When relay IK_R becomes energized, then, relay ILA becomes energized and signal LA is cleared.

45 I will next assume that the operator wishes to place all of the signals at station No. 1 at stop without affecting the position of switch 3. In order to do this, he moves the signal control lever l_q to its middle position, leaving the switch control lever l_p in whichever position it happens to occupy, and operates the starting button OP_1 . The control code then delivered to the line circuit has both the eleventh and twelfth impulses short, as will be plain from the foregoing without tracing the operation in detail. When this code is received at station No. 1, the operation of relay IF_5 during the final impulse of the code, deenergizes either of the directional control relays ILH or IRH which may have been energized and these relays both remain deenergized when relay IF_5 again closes its back contacts. Under these conditions, then, all the signal control relays are deenergized and the signals all indicate stop.

50 It will be plain, from the foregoing that the ninth and tenth impulses in each control code are allocated to the control of the switch at a station, the ninth impulse being prolonged to operate the switch to its normal position and the tenth impulse being prolonged to operate the switch to its reverse position. In similar manner, the eleventh

and twelfth impulses of the control code are allocated to the control of the signal at each station, the eleventh impulse being prolonged to clear the westbound signals, and the twelfth impulse being prolonged to clear the eastbound signals. In any case, the only signal that can be cleared is the signal which governs traffic over the route set up by the position then occupied by the switch. If both the eleventh and twelfth impulses of a control code are short, all signals are 10 placed at stop, independently of traffic conditions at the station.

55 It will be noted that in order to clear a signal, both a route stick relay $INWS$ or $IRWS$ and a traffic direction stick relay ILH or IRH must be 15 picked up by the control code and the circuits are so arranged that it is impossible to clear a signal over a route different from that intended, as a result of a failure of a relay or an omission of an element in the code already due to failure of 20 the switch to operate. In this latter connection, it should be noted that since the indication relay IK_R is controlled not only by the switch circuit controller contacts 9 and 10 but also by contacts of relays $INWS$ and $IRWS$, no signal can be 25 cleared unless the switch occupies the position corresponding to the route set up by the condition of relays $INWS$ and $IRWS$.

30 In all of the preceding discussion, I have considered only the transmission of control codes 30 from the dispatcher's office to station No. 1, and it will be manifest that each of these codes has the first impulse long and also the second and fifth impulses long to pick up relays IL , IG and IS at station No. 1. From an inspection of the 35 drawings, Fig. 3, it will be plain that relay IG is energized by a long second impulse in the code because jumper 143 connects front contact 144 of relay IC_1 with front contact 142 of relay IB_2 . Had jumper 143 connected front contact 144 of 40 relay IC_1 with front contact 190 of relay IB_3 , it would have been necessary to prolong the third impulse of the control code in order to pick up relay IG . Similarly, had the jumper 143 been 45 adjusted to connect front contact 144 of relay IC_1 with front contact 191 of relay IB_4 , relay IG could be energized only if the fourth impulse of the control code were long. Furthermore, by proper adjustment of jumper 148, the apparatus could be arranged to pick up relay IS on codes 50 having the sixth, seventh or eighth impulses long instead of the fifth impulse, as shown in the drawings, by connecting jumper 148 to a corresponding contact of the counting relay chain. It is apparent from the foregoing that the apparatus at the station can be adjusted to respond to any one of twelve different combinations of 55 long impulses in the code and each station will be selected only by the code having the proper combination of long impulses. Since none of the 60 apparatus at a station can be actuated in response to a control code unless the station relay at that station corresponding to relay IS at station No. 1 has been energized, it follows that the station will be unaffected by any code except the 65 one intended for that station, and of course, in practice the jumpers 143 and 148 at each of the 12 stations will be adjusted so that each station will respond to a different code.

70 If a code is to be sent from the dispatcher's 70 office for controlling apparatus at a station other than station No. 1, it may be accomplished by operating apparatus associated with the panel corresponding to such station in the same manner as already described in connection with panel 75

No. 1 at the despatcher's office, the equipment including a set of 12 panels when there are 12 stations to be controlled. In addition each of the 12 main control panels may be provided with an approach panel, such as is illustrated in the drawings associated with panel No. 1, for the purpose of giving the operator additional information which he can not obtain from the main control panel. It will be seen that starting relay OH1 determines, when energized, that the second and fifth impulses of the control code shall be long. If, however, the individual starting relay for a different panel is energized, other impulses are prolonged to select the corresponding station. At the despatcher's office the selection between impulses is accomplished by the group of contacts illustrated at the bottom of Fig. 2, where I have shown the starting relays for all of the 12 panels, although the operating circuits of these relays have been omitted from the drawings for the sake of simplicity. Each of these starting relays controls the selection of its own panel and station in a manner similar to that described for the selection of panel No. 1 and station No. 1 by the operation of relay OH1.

At each station, the delivery relay F5 energized by the final impulse of the code, requires for its operation that the lock-out relay for that station shall have been energized by the first impulse of the code. For example, at station No. 1, relay 1F5 can not be energized during the thirteenth impulse of a control code unless the lock-out relay 1L is energized. Relay 1L becomes energized only if the first impulse of the control code is a long impulse, and this arrangement prevents improper operation of the station delivery relay by an indication code originating at one of the other stations, which indication codes, as will be explained hereinafter, always have the first impulse short.

In the apparatus located at station No. 1, the circuits provide cross-checks between the functions operated by the ninth and tenth impulses, and between the functions operated by the eleventh and twelfth impulses. For example, if the ninth impulse is long to move the switch to its normal position, the apparatus will not operate unless the tenth impulse is short, and similar cross-protection is given between the eleventh and twelfth impulses.

The operator at the despatcher's office may operate several starting buttons in rapid succession and the corresponding control codes will be sent out consecutively and in order. It is therefore possible for an operator having charge of a number of stations to set up a route involving all of these stations, and operate all of the starting buttons. No further action on the part of the operator is necessary, the equipment functioning automatically to deliver the proper control codes to position the apparatus at the several control stations in accordance with the positions of the levers on the panels at the despatcher's office.

The apparatus is also arranged to transmit, from each station, indication codes similar to the control codes for operating indication means at the despatcher's office in response to any change in the condition of the apparatus located at the station. Each indication code gives complete information to the operator concerning the condition of all apparatus at the station at the time that the indication code is transmitted. For the particular system here illustrated, each indication code consists of 16 impulses of which the first is a locking impulse and is always short as distin-

guished from the long impulse which invariably commences a control code. The next seven impulses in each indication code are utilized to select, at the despatcher's office, the panel which corresponds with the station at which the indication code originates. The ninth to the fifteenth impulses in each indication code are used to select indication relays associated with the panel corresponding to the station transmitting the code. The final or sixteenth impulse of the code is prolonged, as in control codes, and serves to actuate the relays controlling the indication lamps and other apparatus associated with the panel in accordance with the condition of the indication relays at the selected panel.

The ninth and tenth impulses are allocated to switch indication, the ninth impulse being long to indicate "switch normal" and the tenth impulse being long to indicate "switch reverse". The twelfth impulse indicates the condition of an approach section adjacent the switch controlled from the main panel, the parts being so arranged that an approach indication lamp on the approach panel associated with the main control panel is lighted when the twelfth impulse is long, but is extinguished if the last indication code received by the panel had a short twelfth impulse. In similar manner the eleventh impulse controls the track indication informing the despatcher of the condition of the track section containing the switch. Thus the lamp 87 on panel No. 1 is lighted if the last indication code received from station No. 1 had a long eleventh impulse, but this lamp is extinguished if the eleventh impulse was short in the last indication code received from station No. 1. The thirteenth, fourteenth and fifteenth impulses in each indication code are utilized to give information concerning both the signals and the track section at the station. The thirteenth impulse is long and the fourteenth and fifteenth impulses are short if the westbound signal is cleared. If all signals are at stop and the section containing the switch is unoccupied the thirteenth and fifteenth impulses are short and the fourteenth impulse is long. If an eastbound signal is clear the thirteenth and fourteenth impulses are short and the fifteenth impulse is long. The thirteenth, fourteenth and fifteenth impulses are all short if the signals are all at stop and the track section is occupied.

The equipment at any station may be set into operation under a number of conditions. The operation of the equipment to transmit an indication code from a station is initiated by energizing the associated master relay M and this takes place—

1. Following a change in position of the track relay, as by the entrance of a train into the switch track section.
2. Following a change in position of the approach relay (relay 1LAA at station No. 1) as by the entrance of a train into the corresponding approach section.

3. Following the reception of any control code from the despatcher's office.

4. Following a change in position of any signal from clear to stop, or vice-versa, not resulting from the reception of the control code or the entrance of a train into the switch track section.
5. Following an operation of the dual selector mechanism of the switch at the station.

In explaining the operation of the apparatus in transmitting an indication code from station No. 1 to the despatcher's office, I will assume that

the apparatus at the station occupies the condition in which it is illustrated in the drawings, that is, switch 3 is normal, the section b-f is unoccupied, and signal 1LA is clear. I will now assume that a train enters section b-f, thereby de-energizing track relay 1TR. For purposes of simplicity, I will assume that this train is wholly within the limits of section b-f so that all approach relays 1RA, 1LBA and 1LAA are energized. The opening of front contact 11 of relay 1TR de-energizes relay 1TP, and also opens the operating circuits for all signals at front contact 192 of relay 1TR (bottom of Fig. 4) so that all signals indicate stop. Relay 1X therefore becomes energized, and relay 1TK is energized over back contact 193 of relay 1TP. Relay 1TK is subsequently maintained in its energized condition by virtue of a stick circuit including its own front contact 194 and back contact 195 of relay 1TD.

Relays 1TD and 1TK control a starting circuit for the code transmitting equipment at station No. 1 which is normally open when these relays are in agreement but is arranged to be closed when either relay is energized if the other relay is de-energized. Under the present conditions, then, the starting circuit is closed, from terminal B, over front contact 196 of relay 1TK, back contact 197 of relay 1TD, back contact 198 of relay 1HD, back contact 199 of relay 1K, back contact 209 of relay 1Ka, and winding of relay 1M to terminal C. It will be plain that the circuit just traced is closed only if relays 1K and 1Ka are both deenergized, so that this circuit is held open if a code is being transmitted over the line circuit. Assuming, however, that the line circuit is clear, relay 1M becomes energized. When this happens, contact 201-201^a opens, and contact 201-201^b closes. This operation of relay 1M disconnects the portion of the line circuit beyond station No. 1 and closes the line circuit, between station No. 1 and the despatcher's office, through a resistance 202 so proportioned as to compensate for the portion of the line circuit which is disconnected. It will also be noted that the line circuit to the despatcher's office now includes back contact 203 of transmitting relay 1T. Under these conditions, all line stations beyond the transmitting station are locked out so that these stations do not receive the indication code being sent to the despatcher's office, nor can one of these stations take possession of the line to interfere with the code being sent to the despatcher's office.

When relay 1M picks up, a pick-up circuit is completed for relay 1T similar to the pick-up circuit previously described in connection with the transmitting relay OT at the despatcher's office, and passing from terminal B, over back contact 141 of relay 1B1, back contact 142 of relay 1B2, back contact 190 of relay 1B3, back contact 191 of relay 1B4, front contact 204 of relay 1M, and winding of relay 1T to terminal C. Relay 1T therefore becomes energized, opening the line circuit and releasing the line relay 1R at the sending station together with the line relays at the despatcher's office and at any stations located between station No. 1 and the despatcher's office. At station No. 1, when relay 1R releases, it operates the counting chain, as described in connection with the despatcher's office. That is to say, the release of relay 1R first picks up relay 1J and relay 1C1. When relay 1J picks up, relays 1B1 and 1Ka become energized and the closing of relay 1B1 completes a circuit

for relay 1K. When relay 1K picks up, relay 1J is de-energized but this relay does not release during the first impulse of the indication code. When relay 1B1 becomes energized, it opens the pick-up circuit for relay 1T at back contact 141 of relay 1B1 and relay 1T releases to close back contact 203 and restore the line circuit to terminate the first impulse. It will be noted that the pick-up circuit for relay 1M was opened when relay 1Ka picked up, but a holding circuit for relay 1M is now closed from terminal B, over front contact 296 of relay 1K, back contact 205 of relay 1L, front contact 296 of relay 1M, front contact 206 of relay 1Ka, and winding of relay 1M to terminal C. This holding circuit maintains relay 1M energized until the transmission of the indication code has been completed. It will be noted that this first impulse of the code is short so that relay 1J does not become energized and relay 1L remains de-energized.

When relay 1T releases, following the energization of relay 1B1, relay 1R becomes energized, thereby energizing relay 1J and picking up relay 1B1a. Relay 1B1 then releases and closes the pick-up circuit for relay 1T to open the line circuit and start the second impulse of the indication code. When relay 1R opens, relay 1B2 becomes energized and relay 1B1a releases. The energization of relay 1B2 interrupts the pick-up circuit for relay 1T but this relay is now held energized by a holding circuit which passes from terminal B, over back contact 141 of relay 1B1, front contact 142 of relay 1B2, jumper 143, front contact 144 of relay 1C1, front contact 145 of relay 1J, front contact 207 of relay 1T, front contact 204 of relay 1M and winding of relay 1T to terminal C. Relay 1T is therefore energized until relay 1J releases. Relay 1J became de-energized when relay 1R released at the beginning of the second impulse, and at the conclusion of the holding time of relay 1J, this relay releases, thereby opening the holding circuit just traced for relay 1T, and de-energizing the latter relay. When relay 1T releases it restores the line circuit to terminate the second impulse.

When relay 1J releases, however, during the second impulse, the closing of back contact 145 of this relay completes a pick-up circuit for relay 1G which is the same as the holding circuit for relay 1T as far as contact 145 of relay 1J, and passes thence over front contact 146 of relay 1C1 and winding of relay 1G to terminal C. Relay 1G is subsequently held up over its stick circuit including its own front contact 147 and contacts 296 and 136 of relays 1K and 1Ka. The length of the second impulse is measured by the consecutive release of relays 1J and 1T. This long impulse is therefore equal to approximately 24 cycles.

At the conclusion of the second impulse, relay 1R picks up and energizes relays 1J and 1B2a. The operation of the equipment during the third and fourth impulses, which are short impulses, will be apparent from the foregoing without tracing the circuits in detail. At the beginning of the fifth impulse, however, relays 1C2 and 1B1 become energized and the pick-up circuit for relay 1T is then interrupted. A holding circuit is now closed for relay 1T, however, from terminal B, over front contact 141 of relay 1B1, jumper 148, front contact 149 of relay 1C2, front contact 145 of relay 1J, front contact 207 of relay 1T, front contact 204 of relay 1M, and winding of relay 1T to terminal C. Due to this holding circuit, the relay 1T is held energized to keep the line cir-

- cuit open until relays IJ and IT release consecutively thereby prolonging the fifth impulse to approximately 24 cycles. When relay IJ releases, a circuit is completed for relay IS which is the same as the holding circuit just traced for relay IT as far as back contact 145 of relay IJ and passes thence over front contact 150 of relay $IC2$, front contact 151 of relay IG and winding of relay IS to terminal C. Relay IS therefore becomes energized and is subsequently stuck up over its own front contact 152 and front contacts 296 and 136 of relays IK and IKa . When relay IT releases to terminate the fifth impulse, the counting relays are again set into operation and the equipment continues to function during the sixth, seventh and eighth impulses to transmit three short impulses to the line circuit. When relay IR becomes de-energized at the beginning of the ninth impulse, relays $IB1$ and $IC3$ are energized. A holding circuit is now completed for relay IT for prolonging this impulse to give a "switch normal" indication at the despatcher's office. This holding circuit passes from terminal B over front contact 208 of relay IKR , normal contact 209 of relay IKR , front contact 210 of relay $IB1$, front contact 211 of relay $IC3$, front contact 145 of relay IJ , front contact 207 of relay IT , front contact 204 of relay IM and winding of relay IT to terminal C. This holding circuit maintains relay IT energized until relay IJ releases, whereupon relay IT releases and the line circuit is restored to terminate the ninth impulse. When relay IJ releases, however, a pick-up circuit is completed for relay $IF1$ from terminal B, over front contact 296 of relay IK , front contact 136 of relay IKa , back contact 137 of relay IJ , front contact 138 of relay $IB1$, front contact 159 of relay IS , front contact 188 of relay $IC3$, and winding of relay $IF1$ to terminal C. Relay $IF1$ is subsequently held up by a stick circuit over its own front contact 189 and front contacts 296 and 136 of relays IK and IKa . When relay IT closes its back contact 203 at the end of the long ninth impulse, relay IR becomes energized and picks up relay $IB1a$. Relay $IB1$ then releases to close its back contact 141 and complete the pick-up circuit for relay IT to start the tenth impulse. When relay IR releases, relay $IB2$ becomes energized and relay $IB1a$ releases. There is no holding circuit for relay IT during the tenth impulse so that the energization of relay $IB2$ de-energizes relay IT , and when this relay releases it restores the line circuit to terminate the tenth impulse, which is therefore short. Relay IR therefore again becomes energized, picking up relay $IB2a$, and relay $IB2$ releases to close its back contact 142 and energize the pick-up circuit for relay IT , thereby opening the line circuit to start the eleventh impulse. When relay IR releases, relay $IB3$ picks up and relay $IB2a$ releases. The eleventh impulse is prolonged to give an "occupied track" indication at the despatcher's office, and to accomplish this result a holding circuit is now completed for relay IT from terminal B, over front contact 212 of relay ITK , front contact 213 of relay $IB3$, front contact 145 of relay IJ , front contact 207 of relay IT , front contact 204 of relay IM , and winding of relay IT to terminal C. This holding circuit maintains relay IT energized until relay IJ releases, whereupon relay IT releases and restores the line circuit to terminate the eleventh impulse. When relay IJ releases, a pick-up circuit is completed for relay $IF3$ from terminal B, over front contact 296 of relay IK , front contact 136 of relay IKa , back contact 137 of relay IJ , front contact 153 of relay IS , front contact 154 of relay $IC3$, front contact 297 of relay $IB3$ and winding of relay $IF3$ to terminal C. Relay $IF3$ is subsequently held energized over a stick circuit including its own front contact and front contacts 296 and 136 of relays IK and IKa .
- The twelfth, thirteenth, fourteenth and fifteenth impulses of the indication code are short and these impulses are produced by operation of the apparatus in a manner similar to that heretofore described and readily understood from the drawings without tracing the operation of the apparatus in detail.
- The sixteenth impulse is the delivery impulse, and at the beginning of this impulse, relay IR releases to pick up relay $IB4$ and release relay $IB3a$. Relay $IC4$ is now energized and a holding circuit is therefore closed for relay IT which does not include a contact of relay IJ but may be traced from terminal B, over back contact 141 of relay $IB1$, back contact 142 of relay $IB2$, back contact 190 of relay $IB3$, front contact 191 of relay $IB4$, front contact 214 of relay $IC4$, front contact 204 of relay IM , and winding of relay IT to terminal C. Relay $IF8$ now becomes energized, its circuit including front contact 215 of relay IM , front contact 216 of relay $IC4$, and front contact 217 of relay $IB4$. When relay $IF8$ becomes energized, a pick-up circuit for relay ITD is completed over front contact 218 of relay $IF8$, and front contact 219 of relay $IF3$. The energization of relay ITD interrupts the stick circuit for relay ITK so that relay ITK is now controlled solely by relay ITP . It follows that if relay ITP had become energized as a result of the train leaving section $b-f$ before the indication code was completed, relay ITK would have been held up over back contact 195 of relay ITD to complete the track occupied code, but relay ITK would release at the completion of the code and this operation would then start the transmission of a new indication code to report this change of condition to the despatcher's office.
- During the long sixteenth impulse, relay IJ is of course de-energized and when it releases, it de-energizes relay IKa . When relay IKa releases it de-energizes relay IM and when relay IM releases, it closes back contact $201-201b$ to terminate the sixteenth impulse and restore the line circuit through the stations more remote from the despatcher's office. As a result, relay IR then picks up to terminate the sixteenth impulse which in the indication code is thus measured by the consecutive release of relays IJ , IKa and IM and is equal to approximately 45 cycles. The opening of relay IM releases relay IT which thereupon becomes de-energized, and the opening of relay IM also de-energizes relay $IF8$, which thereupon releases and completes a stick circuit for relay ITD including back contact 218 of relay $IF8$, front contact 220 of relay ITD . Relay ITD is held energized in agreement with relay ITK which is now energized by its pick-up circuit because relay ITP is assumed to be de-energized as a result of the presence of a train in section $b-f$. Relay ITD remains energized until an indication code is transmitted which does not contain the "occupied track" indication, that is, a long eleventh impulse.
- When relay IR becomes energized, at the end of the sixteenth impulse, relays IJ and IKa pick up consecutively and relay $IB4$ releases, but since relay IT is not now connected in the line circuit,

the line circuit remains closed. Relay $1R$ therefore remains steadily energized and at the expiration of its holding time relay $1K$ releases, thereby de-energizing relays $1G$, $1S$, $1F1$, $1F3$ and $1C4$. The counting chains are now restored to their normal position, and the equipment is in condition to receive a control code from the despatcher's office. When relay $1K$ releases, it also de-energizes relay $1J$. When relay $1J$ releases, it de-energizes relay $1Ka$. When relay $1Ka$ releases, the starting circuits for relay $1M$ are prepared so that relay $1M$ can again pick up to transmit an indication code from station No. 1.

In addition to the circuits already traced for relay $1T$, this relay has another pick-up circuit passing from terminal B, through front contact 221 of relay $1L$, front contact 204 of relay $1M$, and winding of relay $1T$, to terminal C. It might happen under some conditions that the equipment at station No. 1, and the equipment at the despatcher's office should start to deliver codes to the line circuit at the same instant. If this happens, the relay $1T$ at station No. 1 releases first, because relay OT at the office is being held up to prolong the first impulse of the control code. During this long first impulse, then, relay OJ at station No. 1 releases, and picks up relay $1L$ at the station in the manner described hereinbefore. But the opening of back contact 205 of relay $1L$ opens the circuit for relay $1M$ and the closing of front contact 221 of relay $1L$ closes the additional circuit for relay $1T$ just described. The line circuit is therefore opened again at the station, and is held open until relay $1M$ releases. As a result the equipment at the station is placed in condition to receive the control code from the office, and can not take command of the line circuit to deliver its indication code until the line circuit is again clear after the conclusion of this control code. Since relay $1M$ is now open, the line stations beyond station No. 1 are also in condition to receive a control code because the long interval of open circuit of the line circuit to each of these more remote stations has been measured by the consecutive release of relays $1J$ and $1M$ at station No. 1.

It will be seen from the foregoing that the indication code transmitted to the line circuit from a station consists of 16 impulses, similar to those transmitted from the despatcher's office except that the first impulse of the code transmitted from a station is a short impulse, while the control codes transmitted from the office to the station have their first impulses long. In the particular indication code described, the long impulses are the second, fifth, ninth, eleventh and sixteenth.

I will now describe the operation of the equipment at the despatcher's office in response to the reception of the indication code described above. The line relay OR at the office of course follows the interruptions in the line circuit and operates the counting relays and the associated apparatus in the manner similar to that described in connection with the transmission of a control code. During the reception of an indication code, however, relays OT and OM remain de-energized, and the counting relays are controlled solely by the line relay OR . When relay OR releases at the beginning of the first impulse, it picks up relays OJ , $OC1$, $OB1$, OK , OJP , OKa , and $OL1$, as described in connection with the operation of the apparatus during transmission of a control code. Relay OJ is de-energized when relay OK picks up, but since the first impulse of the indication

code is short, relay OJ does not release. It should be particularly pointed out that lock-out relay $OL1$ picks up during this first short impulse because the pick-up circuit for this relay does not include a back contact of relay OJ . When relay OR picks up at the end of the first impulse, relays OJ and $OB1a$ become energized and relay $OB1$ releases. When relay OR opens at the beginning of the second impulse, relay $OB2$ picks up and relay $OB1a$ releases. The second impulse is long and relay OJ releases at the end of its holding interval. This de-energizes relay OJP which subsequently becomes de-energized, but in receiving, relay OJP is cut out, and the indication apparatus is controlled by back contact of relay OJ for reasons which will be described in detail hereinafter. In this present instance, the de-energization of relay OJ completes a pick-up circuit for relay $OG1$ from terminal B, over front contact 56 of relay OK , front contact 115 of relay OKa , back contact 116 of relay OJ , back contact 222 of relay OM , front contact 118 of relay $OB2$, front contact 119 of relay $OL1$, front contact 120 of relay $OC1$, and winding of relay $OG1$ to terminal C. When relay $OG1$ becomes energized, current is supplied over the circuit just traced and front contact 121 of relay $OG1$ and winding of relay $OL2$ to terminal C. Relay $OL2$ therefore becomes energized and completes stick circuits for relays $OL2$ and $OG1$ similar to those previously described in connection with the operation of the apparatus in transmitting a control code.

The third and fourth impulses are short and relay OJ does not release during these impulses. At the beginning of the fifth impulse, relays $OB1$ and $OC2$ are energized and since this impulse is long, relay OJ releases. When this happens, current flows from terminal B, over front contact 56 of relay OK , front contact 115 of relay OKa , back contact 116 of relay OJ , front contact 222 of relay OM , front contact 127 of relay $OB1$, front contact 128 of relay $OC2$, front contact 129 of relay $OG1$, and winding of relay $OS1$ to terminal C. Relay $OS1$ therefore becomes energized and current flows over the circuit just traced and over front contact 130 of relay $OS1$, back contact 131 of relay $OF8$, and winding of relay $OL3$ to terminal C. Relays $OS1$ and $OL3$, having thus been energized, are subsequently maintained in their energized condition by the stick circuits previously described for these relays in explaining the operation during transmission of a control code. The energization of relay $OS1$ breaks the stick circuits for all indication relays associated with panel No. 1 so that these relays are all de-energized and all indication lamps on the panels controlled thereby, that is, panel No. 1 and the associated approach panel are extinguished. The sixth, seventh, and eighth impulses are short and relay OJ does not release during these impulses. Relay OJ was, of course, energized at the end of the fifth impulse. When relay OR releases at the beginning of the ninth impulse, relays $OB1$ and $OC3$ are energized. The ninth impulse is long and relay OJ therefore releases. When this happens, relay $OF1$ becomes energized, the circuit for this relay passing from terminal B, over front contact 56 of relay OK , front contact 115 of relay OKa , back contact 116 of relay OJ , back contact 224 of relay OM , front contact 225 of relay $OC3$, front contact 226 of relay $OB1$, and winding of relay $OF1$ to terminal C. Relay $OF1$ is subsequently held in its energized condition by a stick circuit which passes from terminal B, over front contact 56 of relay 75

OK, front contact 105 of relay OKa, front contact 227 of relay OF1 and winding of relay OF1 to terminal C.

The tenth impulse is short, but the eleventh impulse is long, and during the latter impulse, relays OB3 and OC3 are energized and relay OJ releases. A pick-up circuit is then completed for relay OF3 from terminal B, over front contact 56 of relay OK, front contact 115 of relay OKa, back contact 116 of relay OJ, back contact 224 of relay OM, front contact 225 of relay OC3, front contact 228 of relay OB3 and winding of relay OF3 to terminal C. Relay OF3 is subsequently stuck up over a circuit including its own front contact 229 and front contacts 56 and 105 of relays OK and OKa, respectively. The twelfth, thirteenth, fourteenth and fifteenth impulses of the indication code are short, and these impulses simply step along the counting chains without operating any additional apparatus. During the sixteenth impulse, however, relay OJ releases. The de-energization of relay OJ during the sixteenth impulse picks up relay OF8, current flowing from terminal B, over front contact 56 of relay OK, front contact 115 of relay OKa, back contact 116 of relay OJ, back contact 224 of relay OM, front contact 230 of relay OC4, front contact 231 of relay OB4, and winding of relay OF8 to terminal C. Relay OF8 is subsequently stuck up over its own front contact 232 and front contacts of relays OK and OKa.

When relay OF8 becomes energized, selected indication relays for panel No. 1 are energized in accordance with the energization of relays OF1 to OF7, inclusive. Under the conditions described relays OF1 and OF3 are energized, so that the energization of relay OF8 picks up relays ONW1 and ORT1. The circuit for relay ONW1 may be traced from terminal B, over front contact 233 of relay OF8, front contact 234 of relay OF1, front contact 235 of relay OS1, and winding of relay ONW1 to terminal C. The pick-up circuit for relay ORT1 passes from terminal B, through front contact 233 of relay OF8, front contact 236 of relay OF3, front contact 237 of relay OS1, and winding of relay ORT1 to terminal C. The energization of relay ORT1 closes the circuit for the track occupied indication lamp 87 at front contact 239 and the energization of relay ONW1 completes, at front contact 84 thereon, the circuit for the switch normal indication lamp 88. The lamps 87 and 88 are therefore lighted to indicate to the operator that at station No. 1 corresponding to panel No. 1, the track section is occupied and the switch is normal. Since none of the signal lamps 90, 91 or 92 is lighted the operator knows that all signals at this location are at stop.

When relay OF8 picks up, relay OL3 is de-energized, its stick circuit being interrupted at back contact 131 of relay OF8. Relay OL3 therefore releases and breaks the stick circuit for relay OS1, which also releases. The release of relay OS1 interrupts the pick-up circuits just described for indication relays ONW1 and ORT1, but these relays are now held up by stick circuits including back contact 78-78^b of relay OS1. The stick circuit for relay ONW1 also includes back contact 79 of starting relay OH1.

When relay OR becomes energized at the end of the sixteenth impulse, relay OJ picks up and relay OB4 releases. Relay OR is now steadily energized, however, so that relay OK^a releases, thereby de-energizing relays OJ, OKa, OJP, OF1,

OF3, OF8 and OC4. Relays ONW1 and ORT1 still remain energized.

The equipment at the despatcher's office is in condition to transmit a control code as soon as relay OKa closes its back contact.

The despatcher's office is also provided with an annunciator designated by the reference character 242 which may be controlled in accordance with the track indication of any selected panel. For example, if the operator wishes to have an audible indication of the entrance of a train into the section at station No. 1, he closes the switch 240 on panel No. 1. Under these conditions, when relay ORT1 becomes energized as a result of the energization of relay OF8, current flows from terminal B, over front contact 244 of relay OF8, front contact 241 of relay ORT1, switch 240 and annunciator 242 to terminal C. By means of the switches 240 on the several panels, the track annunciator 242 may be placed under the control of the indication apparatus on any selected panel and an audible signal provided for any desired panel.

Furthermore, the despatcher's office is provided with a graphic train recorder of which only the pen magnets are illustrated in the drawings. Each control panel and each approach panel is provided with a pen magnet which operates in the usual and well known manner to make a permanent record of train movements. The pen magnet for panel No. 1 is designated by the reference character 243 and this magnet is connected in parallel with relay ORT1, so that the magnet is energized when an occupied track indication is displayed on the corresponding panel.

I will next assume that the switch 3 at station No. 1 occupies its reverse position, and that indication relay !KR is energized in its reverse position. I will also assume that the track section b-f is unoccupied, that signal !LA is clear, and that a train enters the approach section f-g to start the transmission of an indication code to the despatcher's office. The entrance of this train into section f-g de-energizes relay !LAA and thereby completes the pick-up circuit for relay !AK at back contact 245 of relay !LAA. When relay !AK picks up, a stick circuit is completed over its own front contact 247 and back contact 246 of relay IAD. Since relay !AK is now energized, and relay !AD is de-energized, a starting circuit is completed for relay !M which may be traced from terminal B, over front contact 248 of relay !AK, back contact 249 of relay IAD, back contact 198 of relay !HD, back contact 199 of relay !K, back contact 200 of relay !KA, and winding of relay !M to terminal C. Relay !M therefore becomes energized and actuates the equipment at station No. 1 to deliver an indication code to the line circuit in a manner similar to that described above. The second and fifth impulses of this indication code are long for the purpose of selecting panel No. 1 at the despatcher's office. The ninth impulse is short, however, because the switch occupies its reverse position. Since relay !KR is now energized in its reverse direction, a holding circuit is completed for relay !T during the tenth impulse from terminal B, over front contact 203 of relay !KR, reverse contact 209 of relay !KR, front contact 250 of relay !B2, front contact 211 of relay !C3, front contact 145 of relay !J, front contact 207 of relay !T, front contact 204 of relay !M and winding of relay !T to terminal C, and as a result of this holding circuit, relay !T is held energized during

ing the tenth impulse to prolong this impulse until relay IJ becomes de-energized. The eleventh impulse is short, because section $b-f$ is unoccupied, but during the twelfth impulse a holding circuit is completed for relay IT from terminal B, (lower right-hand corner of Fig. 3) through front contact 251 of relay IAK , front contact 252 of relay $IB4$, front contact 211 of relay $IC3$, front contact 145 of relay IJ , front contact 207 of relay IT , front contact 204 of relay IM , and winding of relay IT to terminal C. Relay IT is therefore held energized during the twelfth impulse until relay IJ releases, thereby prolonging the twelfth impulse of the indication code.

During the thirteenth impulse, relays $IC4$ and $IB1$ are energized, and since signal ILA is now clear, a holding circuit for relay IT is closed from terminal B, over contact 21 operated by signal IRB , contact 22 operated by signal IRA , contact 23 operated by signal ILA , front contact 253 of relay $IB1$, back contact 254 of relay ITK , front contact 255 of relay $IC4$, front contact 145 of relay IJ , front contact 207 of relay IT , front contact 204 of relay IM , and winding of relay IT to terminal C. By virtue of this circuit, relay IT is held energized during the thirteenth impulse until relay IJ releases, so that the thirteenth impulse of the code is prolonged.

The remaining impulses of the indication code are short until the sixteenth impulse is reached. The sixteenth or final impulse is, of course, prolonged in the manner previously described. It should be observed, however, that the sixteenth impulse energizes relay $IF8$, thereby completing a pick-up circuit for relay IAD , over front contact 256 of relay $IF8$, and front contact 257 of relay $IF4$. Relay IAD therefore becomes energized and breaks the stick circuit for relay IAK . Relay IAK is therefore placed solely under the control of relay ILA . When relay $IF8$ becomes de-energized at the conclusion of the sixteenth impulse, relay IAD is held energized by a stick circuit including its own front contact 259 and back contact 256 of relay $IF8$. Relay IAD subsequently remains energized until a code is transmitted that does not contain the "approach occupied" impulse, that is, an indication code which does not have its twelfth impulse prolonged.

Referring now to the equipment at the dispatcher's office, when the indication code just described is received relay $OS1$ becomes energized during the fifth impulse, thereby de-energizing any indication relays which may happen to be energized, and extinguishing all of the indication lamps on panel No. 1 and the associated approach panel. When the tenth impulse is received, relays $OB2$ and $OC3$ are energized, and since this impulse is long, relay OJ releases, and current flows from terminal B, over front contact 56 of relay OK , front contact 115 of relay OKa , back contact 116 of relay OJ , back contact 224 of relay OM , front contact 225 of relay $OC3$, front contact 260 of relay $OB2$ and winding of relay $OF2$ to terminal C. Relay $OF2$ therefore picks up and is subsequently stuck up over its own front contact 261 and front contacts 56 and 105 of relays OK and OKa , respectively. During the twelfth impulse of the indication code, relay OJ again becomes de-energized, and current flows from terminal B, over front contact 56 of relay OK , front contact 115 of relay OKa , back contact 116 of relay OJ , back contact 224 of relay OM , front contact 225 of relay $OC3$, front contact 262 of relay $OB4$, and winding of relay $OF4$

to terminal C. Relay $OF4$ therefore becomes energized and is subsequently held in this condition over its stick circuit including its own front contact 263 and front contacts of relays OK and OKa . During the thirteenth impulse, which is long, relays $OC4$ and $OB1$ are energized. When relay OJ becomes de-energized during this impulse, current flows from terminal B, over front contact 56 of relay OK , front contact 115 of relay OKa , back contact 116 of relay OJ , back contact 224 of relay OM , front contact 230 of relay $OC4$, front contact 264 of relay $OB1$, and winding of relay $OF5$ to terminal C, thereby energizing relay $OF5$. This relay is provided with a stick circuit including its own front contact 265 and front contacts of relays OK and OKa , by virtue of which circuit, the relay is held in its energized condition.

During the sixteenth impulse of the indication code, relay $OF8$ becomes energized, as described hereinbefore and when this happens, selected indication relays associated with panel No. 1 become energized. Thus relay $ORW1$ is energized over front contact 233 of relay $OF8$ and front contact 266 of relay $OF2$, and front contact 269 of relay $OS1$; relay $ORA1$ is energized over front contact 233 of relay $OF8$, front contact 267 of relay $OF4$, and front contact 268 of relay $OS1$; and relay $OLH1$ is energized over front contact 233 of relay $OF8$, front contact 270 of relay $OF5$ and front contact 271 of relay $OS1$. At the conclusion of the indication code, all of the relays at the dispatcher's office become de-energized except relays $ORW1$, $ORA1$ and $OLH1$, each of these relays being held in its energized condition by virtue of a stick circuit similar to those previously traced for other indication relays, and which will be readily understood from the drawings without tracing these circuits in detail. When relay $ORW1$ becomes energized the switch 40 reverse indication lamp 89 on panel No. 1 is connected with busses 82 and 83 over front contact 272 of relay $ORW1$, and therefore becomes energized; the left-hand signal clear indication lamp 90 is also energized over front contact 85 of relay $OLH1$, and the approach indication lamp 86 is energized over front contact 273 of relay $ORA1$, to indicate that approach section $f-g$ is occupied. All other lamps on the panels associated with station No. 1 are extinguished and the operator is therefore provided with a visual indication of the condition of all of the other apparatus located at station No. 1.

The dispatcher's office is also provided with an approach annunciator 292 arranged to indicate when a train enters an approach section. As here shown annunciator 292 is controlled over front contacts 284 and 294 of relays $OF8$ and $OF4$, respectively, so that the annunciator is operated while relay $OF8$ is energized during the last impulse of an indication code having its twelfth impulse prolonged.

The approach panel shown on Fig. 2 is also provided with a pen magnet 293 of the graphic recorder described hereinbefore. This pen magnet is connected in parallel with relay $ORA1$, and therefore serves to record the entrance of a train into the approach section associated with station No. 1.

Had signal IRB been clear and all other conditions the same, the indication code transmitted from station No. 1 would have been similar to that described above with the exception that the thirteenth impulse would have been short and

the fifteenth impulse would have been long, a holding circuit for relay $1T$ being completed during the fifteenth impulse from terminal B, over contact 21 operated by signal $1RB$, front contact 5 258 of relay $1B3$, back contact 254 of relay $1TK$, front contact 255 of relay $1C4$, front contact 145 of relay $1J$, front contact 207 of relay $1T$, front contact 204 of relay $1M$, and winding of relay $1T$ to terminal C.

10 The indication code delivered to the line circuit under these conditions energizes relay $OF7$ instead of relay $OF5$ at the despatcher's office. When the sixteenth impulse is received, relay $ORH1$ is energized over front contact 233 of relay 15 $OF8$, front contact 274 of relay $OF7$ and front contact 275 of relay $OS1$. The right-hand signal clear indication lamp 92 is therefore lighted over front contact 276 of relay $ORH1$.

Furthermore, if all signals are at stop and the 20 track section $b-f$ is unoccupied when the indication code is sent out, the fourteenth impulse of the code is prolonged, the holding circuit for relay $1T$ then passing from terminal B, over front contact 193 of relay $1TP$, front contact 277

25 of relay $1X$, front contact 278 of relay $1B2$, back contact 254 of relay $1TK$, front contact 255 of relay $1C4$, front contact 145 of relay $1J$, front contact 207 of relay $1T$, front contact 204 of relay $1M$, and winding of relay $1T$ to terminal C.

30 When an indication code containing a long fourteenth impulse is received at the despatcher's office, relay $OF6$ is energized during this fourteenth impulse and when relay $OF8$ becomes energized during the final impulse of the indication 35 code, relay $ONH1$ is energized over a circuit including front contact 233 of relay $OF8$, front contact 279 of relay $OF6$ and front contact 280 of relay $OS1$. When relay $ONH1$ is energized, the signal stop indication lamp 91 is lighted by

40 current supplied thereto over front contact 281 of relay $ONH1$. When lamp 91 is lighted, the operator is informed that all signals at station No. 1 are at stop, and that the section $b-f$ is unoccupied. He also knows, of course, that the 45 section is unoccupied, from the fact that lamp 87 on panel No. 1 is now extinguished. It will be noted that since the control of the switch indication lamps 88 and 89 by impulses 9 and 10 in the indication code give the operator information concerning the route which is set up at the station, the additional information given by lamps 90, 91 and 92 concerning the traffic direction, which is set up at the station, gives him 50 complete information concerning the individual signal which may be cleared at any time. For example, the clearing at either signal $1LB$ or $1LA$ lights lamp 90 on panel No. 1 at the despatcher's office, but if lamp 88 is also lighted, the operator knows that the signal which is clear 55 must be signal $1LA$, whereas, if lamp 89 is lighted he knows that signal $1LB$ is clear. Similarly, if lamp 92 is lighted, and lamp 88 is also lighted, he knows that signal $1RA$ is clear but if lamps 89 and 92 are lighted, he knows that signal $1RB$ 60 is clear. Obviously, if lamp 91 is lighted, he knows that all signals are at stop irrespective of the condition of the switch, as indicated by lamps 88 and 89.

I have stated above that an indication code is 70 transmitted following the reception of any control code from the despatcher's office. This is accomplished by relay $1HD$ which, as previously described, becomes energized at the conclusion of the control code by the energization of relay 75 $1F5$ and is subsequently stuck up over back con-

tact 184 of relay $1F8$. When relay $1HD$ becomes energized and relay $1KR$ subsequently picks up, a circuit is completed for heater 29 of a thermo-sensitive relay $h3$ which circuit includes back contact 210 of relay $1B1$ or back contact 250 of 5 relay $1B2$, depending upon the position of relay $1KR$, and this circuit also includes front contact 282 of relay $1HD$. At the conclusion of a definite time interval after the energization of the heater of relay $h3$, contact 30 of this relay closes, 10 and a starting circuit is then completed over front contact 198 of relay $1HD$ and a normal or reverse contact of relay $1KR$ to energize relay $1M$ and to commence the transmission of a code. Assuming that the switch occupies its normal 15 position and that relay $1KR$ occupies its normal position, this starting circuit may be traced from terminal B, over front contact 208 of relay $1KR$, normal contact 209 of relay $1KR$, back contact 210 of relay $1B1$, front contact 282 of relay $1HD$, 20 contact 30 of relay $h3$, front contact 198 of relay $1HD$, back contact 199 of relay $1K$, back contact 200 of relay $1Ka$, and winding of relay $1M$ to terminal C.

After relay $1M$ becomes energized, as a result 25 of the circuit just traced, the equipment at the station operates to deliver an indication code to the line circuit in a manner which will be obvious from the drawings, this indication code containing elements which actuate the indication means 30 at the despatcher's office to inform the operator concerning the condition of all devices at the station. It will be observed that the starting circuit just described includes a front contact of the indication relay $1KR$. If relay $1HD$ became 35 energized at the conclusion of a control code which changed the position of the switch, it is manifest that an interval of time elapses before the switch attains its final position. The indication relay, however, becomes de-energized as 40 soon as the code is received, and does not again become energized in its new direction until the switch has attained its final position. The starting circuit therefore is not closed until the switch has attained the position corresponding 45 to the last control code received. The closing of the starting circuit is further delayed for an additional time interval represented by the time necessary to operate the thermo-sensitive relay $h3$. The purpose of this additional time interval 50 is to give the signals sufficient time to reach their clear position before the starting circuit is closed. For instance, if the control code reverses the switch and also clears a signal, the switch will be operated first, and the indication relay $1KR$ will 55 then become energized. This completes the circuit for the heater relay $h3$ and also closes the operating circuit for the signal. The relay $h3$ is so proportioned that the time required to close contact 30 of this relay is sufficient to permit the 60 signal to move to clear, so that when the starting circuit does close, the signal has had time to move to its clear position. Of course, if the signal does not move to its clear position, due to the presence of a train or to some defect in its 65 operating mechanism, or for some other cause, the actual position of the signal is indicated at the despatcher's office in the indication code which originates at station No. 1.

At the conclusion of the indication code, relay 70 $1F8$ becomes energized and the opening of back contact 184 of this relay breaks the stick circuit for relay $1HD$ and again de-energizes this relay.

It will be remembered that the locking relay IV is normally energized by a stick circuit which is 75

opened if a train enters any approach section when the signal governing the entrance of traffic into the section *b-f* from such approach section is at clear, and that when relay *IV* is open it is impossible to reverse the switch. When locking relay *IV* becomes de-energized, back contacts *173* and *168* are closed. These contacts *173* and *168* enter into the control of the switch control relays *INWS* and *IRWS*. As shown in the drawings, relay *INWS* is energized over its stick circuit and if relay *IV* now becomes de-energized, relay *INWS* remains energized. If, however, the dispatcher now sends out a code containing a long tenth impulse in an attempt to change the route set up over switch *3*, this code will, of course, have its ninth impulse short. At the conclusion of this control code, the energization of relay *IF5* will break the stick circuit for relay *INWS* and relay *INWS* will release. Relay *IRWS* can not pick up, even though relay *IF2* is energized because the pick-up circuit for relay *IRWS* is open at front contact *168* of relay *IV*. The result of this control code then, is to de-energize the switch control relay which was already energized so that relays *INWS* and *IRWS* are both de-energized. And as a result the indication relay *IKR* is de-energized and both directional control relays *ILH* and *IRH* are de-energized. When the control code is received, it energizes relay *HD* and a starting circuit is now completed from terminal *B*, over back contact *283* of relay *INWS*, back contact *284* of relay *IRWS*, front contact *198* of relay *HD*, back contact *199* of relay *IK*, back contact *200* of relay *IKa*, and winding of relay *IM* to terminal *C*. The equipment at station No. 1 therefore operates to transmit an indication code to the line circuit. Since the indication relay *IKR* is de-energized, both the ninth and tenth impulses of this code will be short. Assuming that the track sections *b-f* and *f-g* are both unoccupied, the eleventh and twelfth impulses will also be short. Since the signals are all at stop, and sections *b-f* is unoccupied, the thirteenth impulse will be long. When this indication code is received at the dispatcher's office, lamp *91* will be lighted and all other lights on panel No. 1 will remain dark. When the operator observes that the only light on panel No. 1 which is lighted is lamp *91*, he knows that the approach locking at station No. 1 is effective.

The approach locking may be released by the operation of the key release at station No. 1 and this is ordinarily done by a member of the crew of the train which approached the section *b-f* and actuated the approach locking. The trainman usually telephones the operator at the dispatcher's office and receives authorization of the operation of the key release. When the key release *k* is operated at station No. 1, a pick-up circuit is completed for relay *IV* over contact *50* of key release *k*. Since all signals at station No. 1 are at stop, the stick circuit for relay *IV* is completed and the key release may be restored to its normal position in which contact *164* is closed. As soon as the operator has been notified that the key release has been operated, he may send out a control code for setting up any additional route or direction control he may desire at station No. 1.

It was suggested hereinbefore that in addition to the control here shown for the signals at the remote stations, these signals may also be controlled by traffic conditions in accordance with the usual automatic block signaling systems. Under these conditions, it sometimes happens, that

a signal moves from clear to stop or from stop to clear independently of any control code delivered from the despatcher's office and independently of any control of track relays at station No. 1. It is desirable that any such change in the condition of a signal should be indicated to the operator and this is accomplished in the following manner. As shown in the drawings, signal *ILA* is clear and relay *HK* is de-energized. If, now, signal *ILA* moves to the stop position, the circuit is completed for relay *IX* and this relay becomes energized. A starting circuit is then completed for relay *IM* which passes from terminal *B*, over front contact *193* of relay *TP*, front contact *271* of relay *IX*, back contact *285* of relay *HK*, back contact *286* of relay *IKa*, back contact *198* of relay *HD*, back contact *199* of relay *IK*, back contact *200* of relay *IKa*, and winding of relay *IM* to terminal *C*. The equipment at station No. 1 therefore operates to deliver an indication code to the line circuit which code controls the indication lamps on panel No. 1 in accordance with the position of the apparatus at station No. 1. It will be noted that an indication code thus delivered to the line circuit is instituted by a change in signal position not resulting from a control code or any change in the condition of the track circuit containing switch *3*. The indication code thus delivered to the line circuit will have a long thirteenth impulse, and when relay *IF8* becomes energized during the final impulse of this indication code, a pick-up circuit is completed for relay *HK*, from terminal *B*, over front contact *193* of relay *TP*, front contact *271* of relay *IX*, front contact *287* of relay *IF8* and winding of relay *HK* to terminal *C*. Relay *HK* therefore becomes energized and when relay *IF8* releases at the conclusion of the sixteenth impulse of the indication code, a stick circuit is closed for relay *HK* over back contact *287* of relay *IF8*, and front contact *288* of relay *HK*. Relay *HK* therefore remains energized until an indication code is transmitted while relay *TP* or relay *IX* is de-energized.

In similar manner, if all signals are at stop at station No. 1 and any signal moves to the clear position, a starting circuit is completed for relay *IM*, over a front contact *285* of relay *HK*. The starting circuit, then closed, is provided with four branches each controlled by a contact on one of the signals at station No. 1. For example, one circuit may be traced from terminal *B*, over contact *21* operated by signal *IRB*, back contact *289* of relay *IKa*, front contact *285* of relay *HK*, back contact *286* of relay *IKa*, back contact *198* of relay *HD*, back contact *199* of relay *IK*, back contact *200* of relay *IKa*, and winding of relay *IM* to terminal *C*. Another branch for this circuit passes from terminal *B*, over contact *21* operated by signal *IRB* and contact *22* operated by signal *IRA* to back contact *289* of relay *IKa*, and thence as before to winding of relay *IM*. Another branch may be traced from terminal *B*, over contact *21* operated by signal *IRB*, contact *22* operated by signal *IRB*, contact *23* operated by signal *ILA* and direct to front contact *285* of relay *HK* and thence as before to winding of relay *IM*. Still another branch may be traced from terminal *B*, over contact *21* operated by signal *IRB*, contact *22* operated by signal *ILA*, contact *23* operated by signal *ILA* and contact *24* operated by signal *IRB* over front contact *285* of relay *HK* as before to the winding of relay *IM*. When any one of the circuits just traced is closed, relay *IM* becomes energized.

and the apparatus at station No. 1 then delivers an indication code to the despatcher's office which has its thirteenth or fifteenth impulse prolonged in accordance with the signal which is clear. At the conclusion of this indication code, relay !F8 becomes energized, thereby opening the stick circuit for relay !HK , and relay !X is now de-energized. The pick-up circuit for relay !HK is not closed during this code, and relay !HK releases.

An indication code may also be initiated by operation of the dual selector mechanism associated with switch 3. Under ordinary conditions of operation, the dual selector mechanism will be operated by a member of the train crew only on authorization from the despatcher's office. When the dual selector mechanism is operated to place the switch 3 under manual control, contacts 5 and 6 of the dual selector mechanism are opened. The opening of contact 6 opens the circuit for motor m , thereby preventing operation of the motor until this contact is again closed. The opening of contact 5 of the dual selector mechanism performs certain other important functions. In the first place, relay !TP becomes de-energized, thereby picking up relay !TK and closing a starting circuit for initiating the delivery of an indication code to the despatcher's office. At the same time, the opening of contact 5 of the dual selector mechanism breaks all stick circuits for the switch control relays !NWS and !RWS and the directional control relays !LH and !RH . Both switch control relays are de-energized and all signals are placed at stop. The indication relay !KR is also de-energized. The indication code delivered to the despatcher's office, under these conditions, therefore, has both its ninth and tenth impulses short but has its eleventh impulse long. As a result, the lamp 87 on panel No. 1 in the despatcher's office is lighted. This distinctive indication informs the operator that the dual selector mechanism at station No. 1 has been operated to remove the switch from the control of the automatic apparatus which is responsive to control codes delivered from the despatcher's office. When the dual selector mechanism is restored to its original position so that contacts 5 and 6 are closed, relay !TP becomes energized if section $b-f$ is unoccupied and this operation of relay !TP closes a starting circuit by de-energizing relay !TK , whereupon an indication code is delivered to the line circuit to extinguish the lamp 87 on the panel No. 1. This indication code has its fourteenth impulse long, however, because relays !TP and !X are both energized, and the lamp 91 in the despatcher's office is lighted. The operator therefore receives visual indication of the fact that the dual selector mechanism has been replaced in its normal position and he may then send out a control code to set up any desired route or direction control at station No. 1.

One feature of my invention is the provision of indication checking means for verifying the condition of apparatus at any station without operating any device at the station. The operator may accomplish this result by simply operating the starting button on the panel corresponding to the station from which he desires information. A control code is then delivered to the line circuit corresponding to the positions which the levers then occupy and, of course, no change is made at the corresponding station except that relay !HD becomes energized during the final impulse of the control code. The ener-

gization of relay !HD operates the thermal relay $h3$ and thereby closes a starting circuit for relay !M at the station which operates to deliver an indication code to the line circuit and actuates the indication relays for the corresponding panel at the despatcher's office. The condition of all apparatus at the station is therefore verified automatically at the panel.

It will be noted that the contacts 30 of the two thermo-sensitive relays $h1$ and $h2$ are included in both the pick-up and stick circuits of the switch control relays !NWS and !RWS , respectively. If, for any reason the switch fails to complete its movement in the time ordinarily sufficient for this operation, the contact of one of the thermo-sensitive relays opens, thereby de-energizing the energized switch control relay !NWS or !RWS . This de-energizes relay !KR and completes a starting circuit as described hereinbefore over back contacts 283 and 284 of relays !NWS and !RWS , respectively. The operator may then send a new code to restore the switch to its original position, and he may then try a second time to operate the switch.

One important feature of my invention is the use of a single code made up of a plurality of impulses to operate all of the functions at a selected one of a plurality of stations or to transmit indications of a plurality of functions from remote stations to a despatcher's office, as described herein.

The use of a single code for these purposes has a number of advantages. One advantage is that the line circuit is used most efficiently. In controlling several functions at a station, in this case a switch and its associated signals, the operator is required to send but a single code to perform any or all of the operations that he may need to accomplish at one time, without repeating the elements of the code which select the particular station. On a busy railroad, individual codes are used for each function, but it may happen that the line is in use constantly and at times considerable delay in the reception of return indications may result, particularly if several indications accumulate at each station. By the use of a single code for operating all functions at one station, the maximum time required to transmit all the accumulated indications at a station is no greater than the time for the transmission of a single indication, and congestion and delay are therefore avoided. Another advantage of this arrangement is that each code sent to a station verifies the positions of all devices at that station and not merely the devices whose positions it is desired to change. Likewise, each indication code verifies the position of the indication apparatus at the office and does not merely change the indication means corresponding to the function which has changed its condition. Still another advantage resides in the elimination of apparatus for starting and sending consecutively a plurality of codes from a station, such as is usually necessary when each code is identified with a particular device or function.

The station apparatus is so arranged that the devices at a station are operated only when the final impulse of the control code is received, and in similar manner the indication apparatus at the despatcher's office is arranged to be operated only when the final impulse of an indication code is received. One advantage of this arrangement is that in case of an error in transmission of a code, so that the code contains an incorrect number of impulses, no change will result in either

indication apparatus or in the condition of functions at a remote station. If the line circuit remains closed for more than a short interval of time during the transmission of a code, the counting relays are restored to their starting positions. For example, if relay $1R$ at station No. 1 is energized for a time greater than the holding interval of relay $1K$, this relay releases and de-energizes all starting relays. Furthermore, if the line circuit remains open for a time appreciably greater than the length of the long impulses in the code, the apparatus is restored to normal by the successive de-energization of relays $1J$ and $1Ka$. For example, if relay $1R$ is de-energized for a time greater than the sum of the release times of relays $1J$ and $1Ka$, the operation of the counting chains is discontinued.

If the line circuit fails while the apparatus at station No. 1 is delivering a code signal to the line circuit, relays $1J$ and $1Ka$ release and interrupt the transmission of the code to the line circuit. These devices provide protection against line interference or interruptions and to insure not only against improper operation as a result of line trouble, but also that a correct code will be transmitted as soon as a closed line circuit is available and all stations in condition to receive a code.

Some mention has been made previously of the operation of the apparatus in case two remote stations commence the delivery of indication codes simultaneously. It should be mentioned that in this contingency the opening of the line circuit at the station closest to the despatcher's office opens the line to all stations beyond for the duration of the code, thereby locking out those stations by holding the relay $1Ka$ at each such station de-energized. When the station nearest the despatcher's office which has an indication stored has delivered its indication code, the line circuit is restored and the next station in order can then deliver its code to the line circuit. In case the despatcher's office and a remote station commence to deliver codes to the line circuit at the same time, the long first impulse in the control code originating at the despatcher's office, gives that station command of the line and the control code is completed, before an indication code can be delivered to the line circuit from any remote station.

I have explained hereinbefore that at the conclusion of a control code originating at the despatcher's office, and following the restoration of the line circuit at the end of the thirteenth impulse, the consecutive release of relays OK and OKa places the despatcher's office equipment in condition to send another code. Referring particularly to station No. 1, at the conclusion of the control code, relays $1K$, $1J$ and $1Ka$ must release consecutively before this station is in condition to transmit an indication code. The apparatus at each of the remaining remote stations is similar to that at station No. 1, and it follows that at the conclusion of a control code, the office equipment is in condition to deliver another code before any remote station can take command of the line. It follows that if an additional panel starting button is operated while a control code is being delivered to the line circuit, the code corresponding to this additional starting button will be delivered to the line circuit immediately upon the completion of the first control code and before any remote station can take possession of the line for delivering an indication code. In similar manner, if an indication code is being delivered to the line circuit, for example by station

No. 1, relays $1K$, $1J$ and $1Ka$ must release consecutively before station No. 1 is in condition to deliver an additional indication code. The office equipment, however, is in condition to transmit a code as soon as relays OK and OKa have released consecutively. It will be plain that with this arrangement, whenever a control code is to be delivered to the line circuit, the office equipment will step in at the conclusion of any code then being supplied to the line circuit and will transmit its control code or codes before any additional indication codes can be supplied to the line circuit.

I have explained hereinbefore that the relay $1J$ and the corresponding relays of the other stations are somewhat slower acting than relay OJ at the despatcher's office. When a control code is being sent from the office, the lengths of the long impulses are measured mainly by consecutive release of relays OJ , OJP and OT . This gives a long impulse of approximately 28 cycles. At station No. 1, relay $1J$ releases at the end of 16 cycles, and the interval from this instant until relay OT at the office again picks up, that is, an interval of approximately 12 cycles, is available to operate the apparatus which must be energized while relay $1J$ is down. When the code originates at the station, however, the long impulses are measured by the consecutive release of relays $1J$ and $1T$ and since relay $1J$ has a release time of approximately 16 cycles and relay $1T$ has a release time of approximately 8 cycles, it will be seen that these long impulses are substantially 24 cycles long. When operating as a receiver, the office equipment shunts the contacts of relay OJP and the apparatus operated during the long impulses is actuated as soon as relay OJ releases. This, of course, happens at the end of 12 cycles, the holding time of relay OJ , and it will be plain that here again an interval of substantially 12 cycles is available during which the apparatus at the despatcher's office which is to be operated during the long impulse may receive its operating impulse. Referring particularly to the apparatus shown on Fig. 2, I have illustrated only one control panel and the associated approach panel. It will be plain, however, that similar panels will be provided in actual practice for each remote station controlled from the despatcher's office. For each of these control panels, there will be provided a series of indication relays corresponding to relays $ONW1$ and $ORW1$, etc., and these relays will be controlled by circuits similar to those here shown for the indication relays for panel No. 1. These additional indication relays will be connected with the wires which terminate in double arrows immediately to the left of the indication relays for panel No. 1.

In order to prevent excessive sparking at the back contacts of the transmitting relays OT , $1T$, etc., which enter the main line circuit in sending codes, I prefer to provide a by-pass connected around each such contact and including a condenser 291 and a resistor 298 .

In describing my invention, I have assumed that 12 stations are controlled from the despatcher's office, but it is apparent that this particular number is not essential. It should be noted, however, that with 12 stations, seven station selecting impulses which are the second to the eighth, inclusive, of each control and indication code, are necessary to distinguish between the several stations. In case the total number of stations is less or greater than 12, a smaller or

large number of station selecting impulses may be necessary in each code.

By way of recapitulation, it may be stated that the system hereinbefore described comprises means for performing both control and indication functions over a single pair of line wires extending from the central office to each of the stations, and normally forming a closed line circuit which may be periodically interrupted at the office to produce a control code, or at any station to produce an indication code. I have illustrated the apparatus as designed for the control of a maximum of twelve stations, and under these conditions the control codes originating at the office each comprise thirteen impulses or intervals of open line circuit, and each indication code originating at a station consists of sixteen impulses. Each impulse of each control and indication code is made either short or long for performing different functions. In the control codes, the first impulse is long and is used as a locking impulse to lock out all field stations and prevent confusion of codes on the line. The next seven impulses of each control code are employed for selecting between the several stations. If the ninth impulse of a control code is long, the switch, at a selected station, is moved to its normal position, but if the tenth impulse is long, the switch is moved to its reverse position. The eleventh and twelfth impulses of each control code are employed for controlling signals at the selected station. I have arranged the apparatus so that if the eleventh impulse is long, a route is established for westbound traffic, and, if the twelfth impulse is long, a route is established for eastbound traffic. If both the eleventh and twelfth impulses are short, all signals are made to indicate "stop". The last impulse of each control code is the operating impulse. The first twelve impulses of a control code establish, or "register", the functions which the code is to perform by picking up certain relays, and when the final impulse is received, certain control circuits are closed in accordance with the conditions which have been registered.

The general plan of the indication codes is similar to the control codes, and the first impulse of each indication code is a short locking impulse. This impulse serves to prevent interference between indication codes from two or more stations, but being a short impulse, permits the apparatus at the office to take command of the line at the conclusion of a code from a station. The next seven impulses following the locking impulse in each indication code are employed to select a particular panel at the office corresponding to the station at which the indication code originated. The ninth and tenth impulses in the indication code inform the despatcher of the condition of the switch at the station, the ninth impulse being prolonged if the switch is normal and the tenth impulse being prolonged if the switch is reversed. The eleventh and twelfth impulses are controlled in accordance with the condition of track circuits at the station, the eleventh impulse being long if the detector track circuit is occupied and short if the detector track circuit is unoccupied. In similar fashion, the twelfth impulse is prolonged if the approach section is occupied but short if the approach section is unoccupied. The thirteenth, fourteenth and fifteenth impulses are controlled to give signal indications, the thirteenth impulse being long if a signal is clear for a westbound move, and the fifteenth impulse being long if a route is set up for an eastbound

move. If the fourteenth impulse is prolonged, an indication is displayed in the office that all signals at the corresponding station are at "stop" and that the detector track section is clear. Furthermore, the thirteenth, fourteenth and fifteenth impulses are all short if the signals are all at stop and the detector track section is occupied.

With this preliminary survey of the general scheme of operation, I will describe briefly the cycles of operation for the control and indication functions.

As shown in the drawings, the switch lever $1p$ is in its normal position and the signal lever $1q$ occupies its left-hand position on panel No. 1 at the despatcher's office. At the corresponding station No. 1, all track sections are unoccupied, switch 3 occupies its normal position, and signal $1LA$ is clear. The condition of the apparatus at station No. 1 is indicated on panel No. 1 at the office by lighted lamps 88 and 90. Lamp 88 indicates that switch 3 is normal and lamp 90 indicates that a signal is cleared for a westbound move. If the operator wishes to reverse switch 3 and to clear signal $1RB$, at station No. 1, he reverses the switch control lever $1p$ and the signal control lever $1q$, and operates the starting button $OP1$. Starting relay $OH1$ then becomes energized, releasing relay $ONW1$ and extinguishing lamp 88. The energization of relay $OH1$ also picks up the master relay OM , which, in turn, initiates the delivery of a control code to the line circuit. The starting relay $OH1$ determines which of the impulses from two to eight are prolonged, different combinations of these impulses being prolonged to select different stations. The lengths of impulses nine to twelve of the control code are regulated by the positions of the signal control lever and the switch control lever. In the present example, station No. 1 is selected and relays $1F2$ and $1F4$ at this station become energized. When the thirteenth impulse is received, relay $1F5$ becomes energized, and the control functions are then performed. In the present instance, relays $1NWS$ and $1LH$ become deenergized, and relays $1RWS$ and $1RH$ pick up. Signal $1LA$ is first restored to stop, then switch 3 is moved to its reverse position, and finally signal $1RB$ is moved to proceed.

It will be understood that other control functions may be produced at station No. 1 by other operations of the levers on panel No. 1, so that any desired combination may be produced at station No. 1. It should also be pointed out that indication codes are initiated at any station by any change in the condition of the apparatus at that station or by the reception of any control code from the despatcher's office. These matters are discussed in detail hereinbefore and will not be repeated here. It should be understood, however, that each station is provided with a plurality of starting circuits any one of which may be closed to initiate the transmission of an indication code from such station. When an indication code is sent from a station, the code first selects apparatus at a particular panel at the despatcher's office, and then picks up one or more of a bank of registering relays designated $OF1$, $OF2$, etc., and shown near the center of Fig. 1. When the final impulse of the indication code is received, certain panel relays are energized depending upon which panel has been selected and which of the registering relays are energized. For example, following the reception of the control code described above, an indication code is delivered to the line circuit by the apparatus at 75

station No. 1; the first impulse of this code locks out the transmitting equipment at the office and at all other stations. The next seven impulses select the corresponding panel No. 1 at the office. 5 Since the switch is reversed, and signal 'RB is cleared at station No. 1, the indication code originating at the station under these conditions will have its tenth and fifteenth impulses prolonged, and these impulses will pick up registering relays 10 OF2 and OF7. During the long sixteenth impulse, then panel relays ORW1 and ORH1 will become energized, and will remain energized after the completion of the indication code. With relay ORW1 energized, lamp 89 is lighted on panel 15 No. 1 at the office to indicate that the switch is reversed, and with relay ORH1 energized, lamp 92 is lighted to indicate that a route is set up for eastbound traffic.

From this brief résumé of the operation of the 20 apparatus for one control and one indication code, it is believed that the operation for other codes will be apparent from the above detailed description.

Although I have herein shown and described 25 only one form of remote controlling apparatus embodying my invention, it is understood that various changes and modifications may be made therein within the scope of the appended claims without departing from the spirit and scope of 30 my invention.

Having thus described my invention, what I claim is:

1. In combination with a line relay arranged at times to be repeatedly energized and de-energized, a chain of relays, a pick-up circuit for the first relay of said chain including a back contact of the line relay, a pick-up circuit for the second relay of the chain including a front contact of said line relay and a front contact 40 of the first relay of the chain, pick-up circuits for each of the remaining relays of the chain each including a front contact of the preceding relay in the chain and a back contact of the second preceding relay in the chain and a contact of said line relay, and a stick circuit for each relay in the chain including a contact of said line relay.

2. In combination, a line relay arranged at 50 times to be repeatedly energized and de-energized, a chain of relays, means for repeatedly energizing and de-energizing the relays of said chain in order, a second chain of relays, means for energizing the first relay of said second chain when said line relay commences to operate, means for subsequently holding said first relay of the second chain energized over a back contact 55 of the second relay of the second chain, means for energizing the second relay of the second chain and each succeeding alternate relay in the chain in order one for each energization of the last relay in the first chain, and means for energizing each of the remaining relays in the second chain when the preceding relay in such chain becomes energized.

3. Remote controlling apparatus comprising a 60 plurality of stations connected by a normally closed line circuit, means for periodically opening said line circuit to produce a code, a chain of counting relays at each station, means responsive to the first interruption of said line circuit for energizing the first relay in each said chain, means for energizing the second relay in each chain provided the first relay in the corresponding chain is picked up and for releasing such 65 first relay in each chain when the line circuit is

next closed, means operating upon each successive opening or closing of the line circuit to energize a succeeding relay in each chain providing the first preceding relay is picked up and the second preceding relay is released, each relay 5 in every chain being released when the succeeding relay in the chain becomes energized.

4. In combination with a transmitting relay, a normally closed line circuit including a back contact of said relay, a chain of counting relays 10 arranged to be repeatedly energized in succession in response to periodic interruptions in said line circuit, a circuit for said transmitting relay including back contacts of all said counting relays, and means for at times holding said transmitting 15 relay energized independently of said circuit.

5. In combination with a transmitting relay, a normally closed line circuit including a back contact of said relay, a chain of counting relays 20 arranged to be repeatedly energized in succession in response to periodic interruptions in said line circuit, manually controlled means for at times supplying current to said transmitting relay over back contacts of all of said counting relays in series, manually controlled means including front contacts of certain of said counting relays for at times energizing said transmitting relay 25 independently of said circuit, and governing means selectively responsive to the time interval during which said line circuit is open. 30

6. In combination with a transmitting relay, a normally closed line circuit including a back contact of said relay, a chain of counting relays arranged to be repeatedly energized in succession in response to periodic interruptions in said line 35 circuit, a second chain of counting relays arranged to be energized in succession by repeated operation of said first chain a different relay of the second chain being energized during each operation of the first chain, manually controlled 40 means for at times supplying current to said transmitting relay through back contacts of all the relays of the first chain in series, a manually operable device, and means effective when one of the relays in said second chain is energized to 45 hold said transmitting relay energized for a brief interval of time when a selected relay in the first chain becomes energized depending upon the condition of said device.

7. In combination with a normally closed line 50 circuit connecting a despatcher's office and a remote station, a first transmitting contact at said office arranged when opened to interrupt said line circuit, means for periodically operating said first contact to supply the line circuit with a control code made up of a plurality of elements, a first relay at the office arranged to be energized each time the line circuit is closed but to be de-energized when the line circuit is continuously 55 open and having slow release characteristics, a repeater relay, a circuit for said repeater relay including a front contact of said first relay, manually controlled means for at times preventing said first transmitting contact from closing until said repeater relay opens to prolong certain elements of a control code, a second transmitter contact at the station, means for periodically operating said second contact to supply the line circuit with an indication code made up of a plurality of elements, a second relay at the station 60 arranged to be energized each time the line circuit is closed but to be de-energized when the line circuit is continuously open and having a retardation time greater than said first relay, means for at times preventing the closing of said second 65 relay. 70

transmitting contact until said second relay opens to prolong certain elements of an indication code, control means at the station actuated during the interval following the opening of the 5 second relay and before the next closing of the first transmitting contact during a control code and selectively controlled in accordance with the element of the control code that is prolonged, and indication means at the office actuated during the 10 interval following the opening of said first relay and the next closing of said second transmitting contact during an indication code and selectively controlled in accordance with the element of the indication code which is prolonged.

15. 8. Remote controlling apparatus comprising a line circuit connecting a despatcher's office and a remote station, a section of railway track at the remote station, two signals one for governing traffic in each direction over said section, means 20 for delivering to said line circuit indication codes having a plurality of impulses, means for prolonging one of said impulses if said section is occupied but not if the section is unoccupied, means for prolonging a second impulse if one of said 25 signals is clear, means for prolonging a third impulse if the other signal is clear, means for prolonging a fourth impulse if said signals are both at stop and said section is unoccupied, and means at said office controlled by said codes for indicating at all times the condition of said section and both said signals in response to the lengths of 30 said four impulses.

9. In combination with a railway switch, two control relays each arranged when energized to 35 operate said switch to a different position, a line circuit, means for supplying different control codes to said line circuit for governing said switch, a first and a second selector relay arranged to be selectively energized in accordance with the characteristics of said code, a delivery relay arranged 40 to be energized at the conclusion of each code, a pick-up circuit for one control relay including front contacts of said first selector relay and of said delivery relay, a pick-up circuit for said 45 second control relay including front contacts of said second selector relay and of said delivery relay, a stick circuit for each control relay including its own front contact and a back contact of said delivery relay.

50. 10. In combination with a line circuit, manually controlled means for supplying different control codes to said line circuit, a series of selector relays arranged to be selectively energized in accordance with the characteristics of the control 55 code supplied to said line circuit, a delivery relay arranged to be energized at the conclusion of each code, a plurality of control relays, a pickup circuit for each control relay including a front contact of said delivery relay and a front contact of a different one of said series of selector 60 relays, a stick circuit for each control relay including its own front contact and a back contact of said delivery relay, and railway traffic governing means selectively controlled by said control 65 relays.

11. In combination with a railway switch, two control relays each arranged when energized to 70 operate said switch to a different position, manually controlled means for energizing a selected one of said relays from a remote point, means for subsequently holding the selected relay in its energized condition after the switch has assumed the corresponding position, an indication relay controlled jointly by said switch and by both said

75 relays, and indication means at said remote point controlled by said indication relay.

12. In combination with a railway switch, two control relays each arranged when energized to 5 operate said switch to a different position, a line circuit, means for supplying different control codes to said line circuit for governing said switch, a first and a second selector relay arranged to be selectively energized in accordance with the characteristics of said code, a delivery relay arranged to be energized at the conclusion of each 10 code, a pick-up circuit for said first control relay including front contacts of said first selector relay and of said delivery relay, a pick-up circuit for said second control relay including front contacts 15 of said second selector relay and of said delivery relay, a stick circuit for each control relay including its own front contact and a back contact of said delivery relay, a polarized indication relay, means for energizing said indication relay in 20 one direction or the other according as one or the other of said control relays is energized provided the switch occupies the corresponding position, and indication means controlled selectively by said indication relay depending upon its condition of energization.

13. In combination with a despatcher's office and a remote station, governing means at such remote station, manually controlled means at said office for delivering different control codes to said 30 station for selectively controlling said governing means, a master relay at such station, means set into operation when said master relay becomes energized to deliver an indication code to said despatcher's office in accordance with the condition 35 of said governing means, a second relay at said station, a pick-up circuit for said second relay arranged to be closed at the conclusion of any control code, a stick circuit for said second relay arranged to be interrupted at the conclusion of an 40 indication code, and means controlled by said second relay for at times energizing said master relay.

14. In combination with a despatcher's office and a remote station, a governing device at such 45 remote station, manually controlled means at said office for delivering different control codes to said station for selectively controlling said device, a first relay at such station arranged to become energized at the conclusion of each control code, 50 and means set into operation when said relay becomes energized and when said device has assumed the position corresponding to the last control code received for delivering to said despatcher's office an indication code corresponding 55 to the position then occupied by such device.

15. In combination with a despatcher's office and a remote station, a plurality of governing devices at such station, manually controlled means at said office for delivering a control code 60 to said station, means at said station for operating selected ones of such devices in a predetermined order in response to said code, means at such station for automatically delivering an indication code to said despatcher's office following a change 65 in the condition of any of such devices, and means effective when the condition of a device changes as a result of a control code to delay the transmission of an indication code until all of such devices have assumed the positions corresponding 70 to said control code.

16. In combination with a despatcher's office and a remote station, governing means at such remote station, manually controlled means at said office for delivering different control codes 75

5 to said station for selectively controlling said governing means, a master relay at such station, means set into operation when said master relay becomes energized to deliver an indication code to said despatcher's office in accordance with the condition of said governing means, a second relay at said station, a pick-up circuit for said second relay arranged to be closed at the conclusion of any control code, and means operating at the 10 expiration of a definite time interval following energization of said second relay to energize said master relay.

17. In combination with a despatcher's office and a remote station, governing means at such 15 remote station, manually controlled means at said office for delivering different control codes to said station for selectively controlling said governing means, a master relay at such station, means set into operation when said master relay becomes energized to deliver an indication code to said despatcher's office in accordance with the condition of said governing means, a second relay at said station, a pick-up circuit for said second relay arranged to be closed at the conclusion of 20 any control code, a thermosensitive relay having a heater controlled by a front contact of said second relay, a contact controlled by said heater, and means controlled by said contact for energizing said master relay.

30 18. In combination with a line circuit, a stretch of railway track, a first relay controlled in accordance with traffic conditions in said stretch, a second relay normally agreeing in position with said first relay, means controlled by contacts of 35 said two relays and set into operation when such relays disagree in position to deliver an indication code to said line circuit, and means responsive to said indication code for operating said second relay into agreement with said first relay.

40 19. In combination with a line circuit, a stretch of railway track, a first relay controlled in accordance with traffic conditions in said stretch, a second relay normally agreeing in position with said first relay, a master relay, means set into operation when said master relay becomes energized to deliver to said line circuit an indication code which depends upon traffic conditions in said stretch, means controlled by said first and second relays for energizing said master relay 45 when said first relay moves out of agreement with said second relay, and means responsive to said indication code to operate said second relay into agreement with said first relay.

50 20. In combination with a section of railway track, a line circuit, a first relay, a second relay, a pick-up circuit for said first relay arranged to be closed when said section is occupied, a stick circuit for said first relay including a back contact of said second relay, means set into operation 55 when either of said first or second relays is energized and the other is de-energized to deliver to said line circuit an indication code which depends upon the condition of said track section, a third relay arranged to be energized during said indication code if said section is occupied, a fourth relay arranged to be energized for a brief interval at the conclusion of an indication code, a pick-up circuit for said second relay including front contacts of said third and fourth relays, and a stick 60 circuit for said second relay including a back contact of said fourth relay.

70 21. In combination with a railway traffic governing device capable of assuming two positions, a line circuit, a first relay, means set into operation if said first relay is energized and said device

moves to one position for delivering a first indication code to said line circuit, means set into operation if said first relay is de-energized and said device moves to its other position for delivering a different indication code to said line circuit, a second relay arranged to be energized for a brief interval at the conclusion of an indication code, means for energizing said first relay if said device occupies said other position when said second relay becomes energized, and a stick 10 circuit for said first relay including its own front contact and a back contact of said second relay.

22. In combination with a railway switch, two relays each arranged when energized to operate said switch to a different position, a signal governing traffic approaching said switch, a normally energized locking relay, means for de-energizing said locking relay if a train approaches said switch when said signal is clear, a manually operable lever, means including said locking relay 15 for selectively controlling said two relays in accordance with the position of said lever, and means controlled by said two relays and by said switch for controlling said signal.

23. In combination with a line circuit, means 20 for supplying to said line circuit different control codes, a railway switch, a first control relay arranged when energized to move the switch to its normal position, a second relay arranged when energized to move the switch to its reverse position, a normally energized locking relay, means for de-energizing said locking relay under certain 25 conditions of traffic adjacent said switch, two code controlled contacts arranged to be selectively closed by said control codes, an additional 30 relay arranged to be energized for a brief interval at the conclusion of each said control code, a pick-up circuit for each of said control relays each including front contacts of said additional 35 relay and said locking relay and an individual 40 one of said code controlled contacts, a stick circuit for each control relay including a back contact of said additional relay, and a second stick circuit for each control relay including a back contact of said locking relay, a front contact of 45 said additional relay and a selected one of said code controlled contacts.

24. Remote controlling apparatus comprising a railway switch, signals for governing traffic over said switch in different directions and routes, 50 means for transmitting a plurality of elements constituting a code, means for controlling one element to determine a route over said switch, means for controlling another element of said code to determine the traffic direction over such 55 switch, means selectively controlled in accordance with the characteristics of said one element for governing said switch, means selectively controlled in accordance with the characteristics of said other element for selectively controlling said 60 signals, and approach locking means operating if a train is approaching said switch when the signal governing said switch is clear to permit a change in the control of said signals while preventing a change in the control of said switch. 65

25. In combination with a transmitting relay, a normally closed line circuit including a back contact of said relay, a series of normally closed contacts arranged to be repeatedly and successively opened and reclosed in response to periodic 70 interruptions in said line circuit, means for at times supplying current through said contacts in series to said transmitting relay, a section of railway track, a railway switch in said section, signals governing traffic over said switch; means 75

for at times holding said transmitting relay energized while selected ones of said contacts are open depending upon the condition of said section, said switch and said signals; and indication

5 means responsive to the relative lengths of impulses covered by periodic interruptions in said line circuit for indicating the condition of said section, said switch and said signals.

26. In combination with a railway switch, two 10 control relays each arranged when energized to operate said switch to a different position, manually controlled means for energizing a selected one of said relays from a remote point, an indication relay, a first circuit for said indication 15 relay controlled by said switch and including a front contact of one said control relay and a back contact of the other control relay, a second circuit for said indication relay controlled by said switch and including a back contact of said one 20 control relay and a front contact of said other control relay, and indication means at said remote point controlled by said indication relay.

27. A selector of the counting relay type comprising a first chain of counting relays, means 25 for operating the relays of said first chain in order through repeated cycles, a second chain of relays including a group relay for each cycle of operation of the first chain and a transfer relay interposed between each two successive 30 group relays, means for energizing the first group relay of the second chain during the first cycle of operation of the first chain, a pick-up circuit for each transfer relay in the second chain each including a front contact of the next preceding 35 relay in the second chain and a front contact of the last relay in the first chain, a pick-up circuit for each group relay except the first including a front contact of the next preceding relay in said second chain, and a stick circuit 40 for each group relay except the last including a back contact of the next succeeding relay in such second chain.

28. A self-checking selector of the counting relay type comprising a two-position control relay 45 periodically operated between said positions, a series of counting relays arranged in order, a pick-up circuit for each alternate counting relay each such circuit except that for the first relay of the series including a front contact of the 50 next preceding relay, a back contact of the second preceding relay and a contact of the control relay closed in one position; a pick-up circuit for each remaining counting relay including a front contact of the next preceding counting relay, and 55 except for the second relay of the series a back contact of the second preceding counting relay; and means for releasing each relay during the operating period of the next succeeding relay.

29. A selector of the counting relay type comprising a two-position control relay at times operated alternately between such two positions, a 60 series of counting relays, a pick-up circuit for the first counting relay closed once only during the first of a series of operations of said control relay and including a contact of the control relay closed in one position, a pick-up circuit for each 65 succeeding alternate counting relay of the series each including a front contact of the next preceding counting relay, a pick-up circuit for each 70 intervening relay of the series each including a front contact of the next preceding counting relay and a contact of the control relay closed in the other position, a holding circuit for each such intervening relay including its own front contact 75 and a contact of the control relay closed in said

other position, and a holding circuit for each alternate relay of the series including its own front contact and except for the last relay a back contact of the next succeeding relay.

30. In a remote control system comprising a 5 normally closed line circuit including a line relay, means for at times opening and closing said line circuit to produce a series of code elements, means for prolonging selected ones of said code elements, a second relay arranged to be energized when said line relay is receiving said code elements, a slow releasing relay having a retardation time less than said prolonged elements but greater than the elements which are not prolonged, a pick-up circuit for said slow releasing 10 relay controlled by back contacts of said line relay and said second relay, a holding circuit for said slow releasing relay controlled by front contacts of said line relay and said second relay, and other means selectively controlled during each 15 code element in accordance with the position of said slow releasing relay.

31. In a remote control system comprising a line circuit including a line relay and supplied 25 with codes made up of long and short line circuit interruptions, a first slow releasing relay having a retardation time less than said long interruptions but greater than said short interruptions, a second slow release relay, a pick-up circuit for said first relay including back contacts 30 of said line relay and said second relay, a pick-up circuit for said second relay including a back contact of said line relay and a front contact of said first relay, whereby the first deenergization of the line relay picks up said first and second 35 relays consecutively and then deenergizes said first relay, a holding circuit for said second relay including a back contact of said line relay and a front contact of such second relay, and a circuit for said first relay including front contacts of 40 said line relay and said second relay, whereby said first relay is energized when said line circuit is closed and deenergized when the line circuit is open, and means controlled by a back contact of said first relay to register long interruptions of said line circuit. 45

32. In combination with a line circuit, a transmitting relay having a contact included in said circuit, a chain of counting relays arranged to be operated in succession in response to periodic 50 interruptions of said line circuit, a circuit for said transmitting relay controlled by certain of said counting relays, and means for at times energizing said transmitting relay independently of said circuit. 55

33. In combination, a line circuit, a transmitting relay having a contact included in said line circuit, a chain of counting relays, means for energizing said counting relays successively in response to repeated opening and closing of said 60 line circuit, means for at times supplying current to said transmitting relay over back contacts of alternate counting relays in series, and means including front contacts of certain of said counting relays for at times energizing said transmitting 65 relay independently of said circuit.

34. In combination with a normally closed line circuit, a line relay included in said circuit, a transmitting relay having a back contact included in said line circuit, a series of counting relays, 70 means for energizing and releasing said counting relays in order in response to consecutive operations of said line relay, and a circuit for said transmitting relay including back contacts of a plurality of said counting relays in series. 75

35. In combination with a line circuit, a code transmitter comprising a line relay included in said circuit, a transmitting relay for periodically controlling said line circuit to actuate said line relay, a series of contacts, means controlled by said line relay for actuating said contacts one at a time in order in response to consecutive similar operations of said line relay, and means including said contacts for controlling said transmitting relay.

36. In combination, with a normally closed line circuit including a line relay, a transmitting relay having a contact included in said line circuit, a series of counting relays arranged to be energized one at a time in sequence in response to consecutive operations of said line relay, the pick-up circuits for alternate counting relays of the series each including a back contact of said line relay and the pick-up circuits for the remaining counting relays each including a front contact of said line relay, and a pick-up circuit for said transmitting relay including back contacts of said alternate counting relays, whereby said transmitting relay is energized to release the line relay and pick up a counting relay thereby opening the transmitting relay circuit to cause repeated periodic interruptions of the line circuit.

37. In combination with a normally closed line circuit including a line relay, a transmitting relay having a contact included in said line circuit, a slow release relay, a series of counting relays, means for operating said relays one at a time in sequence by repeated operation of said line relay, a pick-up circuit for said transmitting relay including back contacts of alternate ones of said counting relays; holding circuits for said transmitting relay each including a front contact of the transmitting relay, a front contact of one of said counting relays, and a front contact of said slow release relay; and means for at times energizing said slow release relay but for de-energizing such relay when any holding circuit for said transmitting relay is closed.

38. In combination with a normally closed line circuit including a line relay, a transmitting relay having a back contact included in said line circuit, a slow release relay, a series of counting relays, means for operating said relays one at a time in sequence by repeated operation of said line relay, a pick-up circuit for said transmitting relay including back contacts of alternate ones of said counting relays; holding circuits for said transmitting relay each including a front contact of the transmitting relay, a front contact of one of said counting relays, and a front contact of said slow release relay; and an energizing circuit for said slow release relay including a front contact of said line relay, whereby said transmitting relay is controlled by said counting relays to deliver to said line circuit consecutive elements of a code selected ones of which are prolonged until said slow release relay opens.

39. A centralized traffic control system for railroads comprising a despatcher's office and a plurality of remote stations connected by line wires, a plurality of traffic governing devices at each station, a plurality of panels at said office one corresponding to each station and each provided with a panel selector relay and a plurality of levers, a plurality of indication devices associated with each said panel, a station selector relay at each station, control means operating over said line wires for simultaneously operating the selector relay at any station and the selector

relay at the corresponding office panel without operating the selector relays at any other station or panel, means for initiating operation of said control means from said office or from said station, means effective when said operation is initiated from said office for controlling the governing devices at the selected station in accordance with the conditions of the levers at the selected panel, and means effective when said operation is initiated from said station for controlling the indication devices at the selected panel in accordance with traffic conditions at the selected station.

40. A centralized traffic control system for railroads comprising a despatcher's office and a plurality of stations connected by line wires, a plurality of traffic governing devices at each station, a plurality of panels at said office one corresponding to each station and each provided with a panel selector relay and a plurality of levers, a plurality of indication devices associated with each panel, a station selector relay at each station, a master relay at the office and at each station, starting means associated with each panel for operating said office master relay, means operating over said line wires and controlled by said starting means and said master relay for selectively energizing the selector relays at the corresponding panel and station and thereafter controlling the governing devices at the selected station in accordance with the conditions of the levers at the selected panel, means at each station for operating the associated master relay, means operating over said line wires and controlled by any station master relay for selectively energizing the selector relays of the corresponding station and panel and thereafter controlling the indication devices on the selected panel in accordance with the traffic conditions at the selected station.

41. A system of railway traffic route signaling comprising a switch and a plurality of signals, a pair of route stick relays and a pair of traffic direction stick relays each adapted to be energized by a momentary current impulse, means for simultaneously energizing one relay of each pair, and circuits for said signals controlled by said relays and closed only when one relay of each pair is energized.

42. A system of railway traffic route signaling comprising a switch and a plurality of signals, a pair of route stick relays and a pair of traffic direction stick relays each adapted to be energized by a momentary current impulse, means controlled from a remote point for simultaneously energizing one relay of each pair, means controlled by said route stick relays for governing the position of said switch, and circuits for said signals selectively controlled by said relays and each closed only when one relay of each pair is energized.

43. In a remote control system for railroads, a stretch of railway track having a siding and a main track; four signals for governing traffic into the main track, into the siding, out of the main track, and out of the siding, respectively; a pair of route stick relays and a pair of traffic direction stick relays, means controlled from a remote point for energizing one only of each pair of relays at a time, means effective when one of said route stick relays is energized for operating said first or said third signal according as one or the other of said traffic direction stick relays is energized, and means effective when the other of said route stick relays is energized for

- operating said second or said fourth signal according as one or the other of said traffic direction stick relays is energized.
44. In combination with a source of different indication codes, a series of register relays arranged to be selectively energized in accordance with the characteristics of each indication code, a delivery relay arranged to be energized at the conclusion of each complete indication code, a plurality of control panels each provided with a panel relay and a plurality of indication relays one for each register relay, means responsive to each indication code for energizing a selected one of said panel relays; a pick-up circuit for each indication relay including front contacts of the corresponding register relay, the associated panel relay, and said delivery relay; and a stick circuit for each indication relay including a back contact of the associated panel relay.
45. In combination with a source of different codes, a register relay selectively responsive to the characteristics of each said code, a delivery relay arranged to be energized at the conclusion of each complete code, an indication relay and a selector relay, means responsive to a code from said source for selectively energizing said selector relay, means effective when said delivery relay picks up to energize said indication relay provided said selector relay and said register relay are energized, and a stick circuit for said indication relay controlled by said selector relay.
46. In a train despatching system for railroads, the combination with a track switch, of a relay controlled from a remote point, a switch machine controlled by said relay and provided with a dual selector for selectively conditioning said switch for operation manually or by said machine, and means controlled by said dual selector for preventing operation of said relay from said remote point when said switch is conditioned for manual operation.
47. In a train despatching system for railroads, the combination with a despatcher's office, of a track switch located at a point remote from said office, a switch machine controlled from said office and provided with a dual selector for selectively conditioning the switch for operation manually or by said machine, means for indicating at said office the condition of said switch when said switch is conditioned for operation by said machine, and means for giving a distinctive indication in said office when the switch is conditioned for manual operation.
48. In a train despatching system for railroads, the combination with a despatcher's office, of a track switch located at a remote point, a switch machine controlled from said office and provided with a dual selector operable to one position for conditioning the switch for manual operation and to another position for conditioning the switch for operation by said machine, means for indicating at said office when said dual selector is moved to said one position, and other means for indicating at said office when the dual selector is moved to said other position.
49. In a remote control system for railroads, a track switch, a first device for operating the switch to its normal position, a second device for operating the switch to its reverse position, means controlled from a remote point for momentarily selectively energizing said devices, means for subsequently holding the selected device in its energized condition, and two overload mechanisms one for each said device each arranged to deenergize the corresponding device when the switch becomes stalled.
50. In a remote control system for railroads, a track switch, a control device, a motor for operating said switch, means controlled from a remote point for momentarily energizing said control device, holding means for subsequently maintaining said control device in its energized condition, a circuit for said motor closed when said control device is energized and opened when the switch has moved to a position of agreement with said control device, and means for disabling said holding means if the motor becomes energized but fails to move the switch into agreement with the control device in a predetermined time.
51. In a remote control system, a railway switch, a motor for operating said switch, control means operated from a remote point for governing said motor, means for indicating at said remote point the completion of an operation of said switch in response to an operation of said control means, protecting means for deenergizing said motor in the event it fails to complete said operation of said switch, and means for indicating at said remote point the operation of said protecting means.
52. In a remote control system, a railway switch, two stick relays, pick-up circuits for said relays selectively controlled from a remote point, a stick circuit for each said relay controlled by conditions adjacent the switch, a motor controlled by said two stick relays for operating said switch, means effective upon the completion of an operation of the switch to indicate the position of the switch at said remote point, and other means for indicating at said remote point when both said stick relays are deenergized.
53. In combination with a line circuit, a section of railway track provided with a track circuit, means for transmitting to said line circuit an indication of the condition of occupancy of said track section, a first relay controlled in accordance with the condition of said track circuit provided said line circuit is available for the transmission of indications, a second relay associated with said first relay controlled selectively in accordance with the last indication transmitted, means controlled by said two relays when said line is available and the condition of the track circuit disagrees with the indication last transmitted for initiating the transmission of an indication of the condition of said track circuit to said line circuit, and means controlled by said second relay provided said track section becomes occupied when said line circuit is not available for the transmission of indications for holding said first relay in the track occupied position until a track occupied indication has been transmitted even though said track circuit is unoccupied when the line circuit becomes available, whereby the transmission of an indication of every entrance of a train into said section is assured.
54. In combination with a main section and an approach section of railway track, a track switch in said main section, a signal governing traffic approaching said switch through said approach section and controlled from a remote point, a stick relay having a stick circuit closed when said signal is clear provided said approach section is unoccupied, a control device at the switch, means controlled from said remote point for at times energizing said control device; means for operating said switch effective only when said main sec-

tion is unoccupied, said stick relay is energized, and said control device is energized; a manually operable mechanism adjacent the switch, and means responsive to an operation of said mechanism for causing said signal to indicate stop and to pick up said stick relay even though a train occupies said approach section.

55. In combination with a railway switch and an approach section of track adjacent the switch, a signal governing traffic approaching the switch through said approach section, a device for controlling said signal, means controlled from a remote point for governing said device, a locking relay having a circuit closed when said signal is clear and said approach section is unoccupied, manually controlled means at said switch for de-energizing said device and for picking up said locking relay, and means controlled by said locking relay for controlling said switch.

56. In a power interlocking system, a switch machine, means permitting hand operation of the switch machine and including a manually movable member which must be shifted before this machine can be operated by hand, electrically operable power control means for cutting off the supply of power to said switch machine controlled electrically and rendered effective by the movement of said member, said power control means when once operated remaining in that condition until specially restored, and manually operable means for restoring said power control means.

57. In a power locking system, a switch machine having contacts opened to permit hand operation thereof, a normally energized stick relay acting when deenergized to interrupt the supply of power to said switch machine, a stick circuit for said relay including said contacts, a manually operable reset circuit controller, and a pick-up circuit for said relay including said circuit controller.

58. In a power interlocking system, a switch machine having a contact opened when it is operated by hand, a detector track circuit, a stick relay having its stick circuit broken by the opening of said contact, a power control device for cutting off the supply of power to said switch machine, said device being actuated by said stick relay when deenergized and by said detector track circuit when occupied, and a manually operable circuit controller movable to establish a pick-up circuit for said stick relay, said circuit controller when in its moved position rendering said power control device effective to cut off the supply of power to the switch machine.

59. A system for protecting power operated switch machines comprising a switch machine having a contact opened to permit hand operation thereof, a normally energized stick relay acting when deenergized to prevent operation of said switch machine, a stick circuit for said relay including said contact, a manually operable reset circuit controller movable to a restoring position to establish a pick-up circuit for said stick relay, and means associated with said circuit controller for independently preventing operation of the switch machine while said circuit controller is in its restoring position.

60. In a system of the type described, a switch machine provided with means for permitting its hand operation and having a selector contact which must be opened before said switch machine can be operated by hand, a control lever for governing the operation of said switch machine, a detector track relay, a normally energized stick relay having a stick circuit including said selector

contact, a power control relay governing the supply of current to said switch machine, an energizing circuit for said power control relay including a front contact of said stick relay and a front contact of said detector track relay; and a manually operable reset circuit controller, having a normally closed contact controlling said energizing circuit for said power control relay, and having a normally open contact controlling a pick-up circuit for said stick relay.

61. In a centralized traffic control system for railroads, a line circuit, a section of railway track, a first relay having a pick-up circuit closed when said track section is occupied, means controlled by said first relay for transmitting over said line circuit a track occupied indication when said first relay is energized and a track clear indication when said first relay is deenergized, a second relay, holding means controlled by said second relay for retaining said first relay energized regardless of the opening of said pick-up circuit in the event said section becomes unoccupied while said line circuit is not available for transmission of indications, and means for controlling said second relay by said transmitting means.

62. In a centralized traffic controlling system for railroads comprising an office and a station, the combination with a transmitter at said station for transmitting indications to said office, of a relay which if energized causes the transmitted indication to be of one character and if deenergized causes such indication to be of a different character, means at said station for selectively controlling said relay, means for initiating the operation of said transmitter when said relay is actuated to a position out of correspondence with the character of the indication last transmitted, and means effective when said relay is energized for preventing deenergization thereof until an indication of said one character has been transmitted.

63. In a centralized traffic controlling system for railroads comprising an office and a station, the combination with a transmitter at said station for transmitting indications to said office, of a relay which if energized causes the transmission of an indication of one character and if deenergized causes the transmission of an indication of a different character, a holding circuit for said relay including a front contact of said relay, a pick-up circuit for said relay controlled by traffic conditions adjacent said station, and means selectively responsive to the character of the transmitted indication for preparing said holding circuit when an indication of said different character is transmitted and for opening said holding circuit when an indication of said one character is transmitted.

64. In a centralized traffic controlling system for railroads comprising an office and a station, the combination with a transmitter at said station for transmitting indications to said office, of a stick relay which if energized causes the transmission of an indication of one character and if deenergized causes the transmission of an indication of a different character, a track section at said station provided with a track relay, a pick-up circuit for said stick relay controlled by said track relay and closed when said section is occupied, and a holding circuit for said stick relay including its own front contact and a contact which is opened or closed, depending upon whether the indication last transmitted by said

transmitter is of said one character or of said different character.

65. In combination with a despatcher's office and a station, a plurality of movable devices at said station, transmitting means at said station for delivering to the office an indication code the character of which depends upon the conditions of said devices, an indication lamp at the office, means selectively responsive to an indication code from said station to energize said indication lamp to signify the condition of a corresponding device at the station, and means responsive to an indication code from said station not arranged to produce a permanent change in the condition 15 of said indication lamp for briefly interrupting the circuit for said lamp.

66. In a remote control system, a despatcher's office and a station, a movable device at said station, means at the station for transmitting indication codes in accordance with the condition 20 of said device, an indication relay at said office for each position of said device, means controlled by said indication codes for selectively energizing said indication relays, a stick circuit for each indication relay operating to hold the relay energized after the termination of the corresponding indication code, manually controlled means at the office for initiating the transmission of a control code to the station for operating said device, and means effective when said manually controlled means is operated for breaking all said 25 stick circuits.

67. In combination, a normally at rest communication system capable of transmitting controls and indications between a control office and a field station when initiated into operation, a master relay at the field station for initiating said system into operation for the transmission of indications when such master relay is conditioned, a plurality of devices, means for conditioning said master relay when any one of said devices changes its condition, operating means responsive to controls received over said system for changing the condition of certain of said 40 plurality of devices, indication checking means set into operation when controls are received by said operating means to condition said master relay but requiring a longer time to complete such operation than is required for the response of said 45 certain of said plurality of devices, means for restoring said indication checking means when said master relay is conditioned, and transmitting means for causing indications of the conditions of said plurality of devices to be transmitted 50 over said system when said master relay is conditioned.

68. In combination, a normally at rest communication system extending from a control office to a field station, a plurality of devices at 60 the field station, certain ones of which receive controls when said system is initiated at the control office, and all of which transmit indications to the control office when said system is initiated at the field station, a master relay for initiating said system at the field station when such master relay is conditioned, indication checking means set into operation to condition said master relay when controls are received by one of said devices but requiring a predetermined 65 time to complete such operation which time is greater than the time required for the response of said device to its controls, means for conditioning such master relay whenever said one device changes its condition, means restoring and preventing further operation of said indication 70 75

checking means whenever said master relay is conditioned, whereby the failure of said device to condition said master relay upon the reception of controls results in the transmission of indications after said predetermined time.

69. In combination with a despatcher's office and a remote station, governing means at such remote station, manually controlled means at the office for delivering different control codes to said station for selectively controlling said governing means, a master relay and a second relay at said station, a pick-up circuit for said second relay arranged to be closed at the conclusion of any control code, a stick circuit for said second relay, means set into operation when said master relay is operated to deliver an indication code to said despatcher's office in accordance with the condition of said governing means and to also open the stick circuit for said second relay, and means controlled by said second relay for at 20 times operating said master relay.

70. In a centralized traffic controlling system for railroads, a line circuit having a plurality of different code combinations of electric impulses impressed thereon, code receiving relays each 25 having only one normal and only one off normal position and always returning to normal after the reception of a code over said line circuit, means for storing the last code combination received until a subsequent combination is received, 30 a track switch, signals governing traffic over said track switch, and means for governing said track switch and said signals in accordance with each different code combination stored in said code storing means only when a complete code is 35 stored therein.

71. The combination; in a centralized traffic controlling system for railroads in which series of impulses of distinctive character are transmitted over a line circuit to form codes; of a code receiving device; a plurality of code registering relays; a track switch and signals therefor; means for successively connecting each of said relays to said device, each connection being made in response to one of said impulses; means responsive to the character of an appropriate impulse for selectively operating the appropriate relay; storing means for storing the positions assumed by said relays during one series of impulses; means for restoring said storing means during a succeeding series of impulses; and means controlled by said storing means for governing the operation of said track switch and signals.

72. In a centralized traffic controlling system for railroads, a line circuit having a plurality of different code combinations of direct current impulses impressed thereon, code receiving means selectively responsive to said impulses and always returning to normal after the reception of a code over said line circuit, means for storing the last code combination received until a subsequent code combination is received, a track switch, signals for governing traffic over said track switch, and means for governing said track 60 switch and said signals in accordance with each different code combination stored in said code storing means only when a complete code is 65 stored therein.

73. In a centralized traffic controlling system 70 for railroads, a line circuit having a plurality of different code combinations impressed thereon each code combination comprising a series of impulses of electric current, a selector responsive to said code combinations, code receiving means se- 75

lected by said selector and responsive to said code combinations, means for restoring said selector and said code receiving means to normal after the reception of a code combination, storing 5 means selected by said selector and said code receiving means for storing the last code combination received until a subsequent code combination is received, a track switch, signals for governing traffic over said track switch, and 10 means controlled by said storing means for governing said track switch and said signals only when a complete code is stored therein.

74. The combination; in a centralized traffic controlling system for railroads in which series 15 of impulses of distinctive character are transmitted over a line circuit to form codes; of a code receiving device having a contact controlled in accordance with the character of each impulse of said series in turn; a plurality of code registering relays; a track switch and signals therefore; means for successively connecting said relays to said contact, each connection being made in response to one of said impulses, to control said relays in accordance with the characters of 20 the appropriate impulses of said series; storing means for storing the positions assumed by said relays during one series of impulses; means for restoring said storing means during a succeeding series of impulses; and means controlled by said 25 30 storing means for governing the operation of said track switch and signals.

75. In a centralized traffic controlling system, a control office, a plurality of field stations, step-by-step means in the control office and at each 35 field station operated synchronously, a message circuit extending to each field station, a plurality of traffic controlling devices at each field station, transmitting means at each field station for transmitting indications over said message circuit 40 of the condition of said traffic controlling devices at that station, and means at each station preventing operation of said transmitting means until the indications of a plurality of said traffic controlling devices are ready for transmission.

76. In a centralized traffic controlling system, a control office, a plurality of field stations, a communication system connecting said control office to each of said field stations, a plurality of traffic controlling devices at each of said field 50 stations, control means in said control office for transmitting controls to any one or several of said traffic controlling devices, and indication means at each field station for automatically transmitting indications to said control office of the condition of said traffic controlling devices at that field station each time any one or several of said traffic controlling devices changes its condition in response to a control only when the changed conditions of all of such devices correspond respectively to the controls transmitted to such devices.

77. In a centralized traffic control system for railroads; a control office and a field station; a communication system connecting said control office and said field station; a plurality of traffic 65 controlling devices at said field station; control means at said field station for each of said traffic controlling devices said control means being manually governed through the medium of said communication system; automatic means for transmitting independently of the manual governing of said control means, through the medium of said communication system the indications of the condition of said traffic controlling devices each time said traffic controlling devices are operated into correspondence with their respective 70 75

control means, and means for preventing the transmission by said automatic means until said devices are in correspondence with their respective control means.

78. In a centralized traffic control system, a power-operated switch machine and a control lever therefor, a normally at rest communication system of the multiple impulse type for transmitting indications of the position of said switch to a distant control office, a switch control relay in the field controlled by contacts of said switch lever, and means governed by said control relay for automatically initiating operation of said communication system only when said switch is operated into agreement with said control relay. 15

79. In a remote control system, a control office, a field station, a line circuit connecting said control office and said field station, means for impressing a series of impulses on said line circuit, means at said control office and at said field station for simultaneously marking the beginning of said series of impulses but marking the end of said series of impulses at said control office and at said field station successively in that order, and means at said control office for initiating 20 25 a second series of impulses prior to the marking of the end of the first series at said field station.

80. In combination; a first slow acting relay and a second slow acting relay, an energizing circuit for said first slow acting relay and an energizing circuit for said second slow acting relay closed simultaneously in response to the operation of a third relay; and an energizing circuit for said second slow acting relay opened by said first slow acting relay when said first slow acting relay releases, whereby said slow acting relays pick up their contacts at substantially the same time and drop their contacts in succession under control of said third relay. 30 35

81. In a remote control system, a control office, a field station, a line circuit connecting said control office and said field station, transmitting means at said control office for impressing a plurality of series of distinctive impulses on said line circuit, transmitting means at said field station for simultaneously marking the beginning of each of said series of impulses but demarking the end of each of said series at said control office and at said field station successively, and means controlled by said cycle demarking means in a manner to render said transmitting means at said control office superior to the transmitting means at said station. 40 45 50 55

82. In a remote control system for railroads, a control office, a field station, a line circuit connecting said control office and said field station, transmitting means at said control office for impressing a plurality of series of distinctive impulses on said line circuit, transmitting means at said field station for impressing a plurality of distinctive impulses on said line circuit, cycle defining means at said control office and at said field station for simultaneously defining the beginning of each of said series of impulses but defining the end of each series at said control office and at said field station successively, and means controlled by said cycle defining means to render 60 65 70 75 said transmitting means at said control office effective and said transmitting means at said field station ineffective only until said transmitting means in said control office ceases to operate.

83. In combination with a railway switch, sig- 75

nals for governing traffic movements over the switch, control means for operating the switch, a polarized switch indication relay, means for energizing said indication relay in one direction or the other in accordance with the position of the switch but only if the switch and its control means occupy corresponding positions, and means controlled by said indication relay for selectively controlling said signals.

10 84. In combination with a railway switch, signals for governing traffic movements over the switch, two control relays each arranged when energized to operate said switch to a corresponding position, manually controlled means for energizing a selected one of said relays from a remote point, means for subsequently holding the selected relay in its energized condition after the switch has assumed the corresponding position, a polarized switch indication relay, a circuit controlled jointly by said switch and by both said relays for energizing said indication relay in a direction corresponding to the position of the switch but only when the switch position corresponds to the condition of said control relays, and means controlled by said indication relay for selectively controlling said signals.

85. A selector of the counting relay type comprising a control relay, a series of counting relays, a pick-up circuit for the first relay of the series including a contact of said control relay closed in one position, pickup circuits for the third and for each succeeding alternate counting relay of the series each including a front contact of the next preceding counting relay, a back contact of the second preceding counting relay and a contact of said control relay closed in said one position, a pickup circuit for the second relay of the series including a front contact of said first relay and a contact of said control relay closed in another position, pickup circuits for the remaining relays of the series each including a front contact of the next preceding counting relay, a back contact of the second preceding counting relay, and a contact of the control relay closed in said another position, and a stick circuit for each counting relay including a contact of said control relay.

86. In combination with a normally closed line circuit including a line relay, a transmitting relay having a contact included in said line circuit, a series of counting relays, means for operating said counting relays one at a time in sequence in response to repeated operations of said line relay, a pickup circuit for said transmitting relay including back contacts of alternate ones of said counting relays; a slow release relay, code selecting means for establishing a plurality of holding circuits for said transmitting relay each including a front contact of said slow release relay and a contact of a selected one of said counting relays; means for at times energizing said slow release relay but for deenergizing such relay when any holding circuit is closed, whereby the transmitting relay delivers to the line circuit consecutive code elements certain of which are prolonged in accordance with the particular counting relays having contacts included in said holding circuits.

87. In combination, transmitting means for delivering to a line circuit a code comprising a series of elements arranged in two groups each having a selected pattern, a receiver controlled over said line circuit and responsive to said code, a plurality of stick relays having pickup and stick circuits and arranged in similar groups, a selector relay for each group of stick relays, means

effective when the receiver is supplied with said code for energizing a particular selector relay in accordance with the code pattern of one group of code elements, and means controlled by the energized selector relay for briefly opening the stick circuits for all the stick relays of the associated group and at the same time closing the pickup circuits for selected relays of said group in accordance with the code pattern of the second group of elements in said code.

88. In combination, transmitting means for delivering to a line circuit a code comprising a series of elements arranged in two groups each having a selected pattern, a receiver controlled over said line circuit and responsive to said code, a plurality of stick relays having pickup and stick circuits and arranged in similar groups, a plurality of bus wires including one wire for each stick relay of a group, each bus wire being included in the pickup circuits for corresponding relays of different groups, a selector relay for each group of stick relays, means effective when the receiver is supplied with said code for briefly energizing a particular selector relay in accordance with the code pattern of one group of code elements and for energizing said bus wires in accordance with the code pattern of the second group of code elements, and means effective as long as said particular selector relay is energized to open the stick circuits for all of the stick relays of the associated group and at the same time to connect each such stick relay to the corresponding bus wire to complete the pickup circuits for selected relays of said group.

89. In combination, transmitting means for delivering to a line circuit a code comprising a series of elements arranged in a selected pattern in two groups, a receiver controlled over said line circuit and responsive to said code, a code delivery relay, a plurality of selector relays, a group of stick relays having pickup and stick circuits for each selector relay, means for energizing said delivery relay when the receiver is supplied with the final element of said code, means for energizing a particular selector relay when the receiver is supplied with one group of code elements selectively arranged in accordance with a particular pattern, means effective when said selector relay is energized to briefly open the stick circuits for all the stick relays of its group, and means effective when said delivery relay is energized for closing the pickup circuits for selected stick relays of said group in accordance with the code pattern of the second group of elements in said code.

90. In combination with a detector section of railway track including a track switch, a switch machine provided with a dual selector for selectively conditioning the switch for manual operation or for operation by said switch machine, means at a remote point for controlling said switch machine, indication means at said remote point for indicating whether said detector section is clear or occupied, and means controlled by said dual selector for controlling said indication means in accordance with the condition of said detector section when the switch is conditioned for power operation and for causing said indication means to indicate the occupied condition of said detector section when the switch is conditioned for manual operation.

91. In a railway train despatching system, the combination with a despatcher's office, of a track switch located at a point remote from said office, a stick relay, means for momentarily energizing

5 said stick relay, a stick circuit for subsequently holding said relay in its energized condition, a switch machine controlled by said stick relay and provided with a dual selector operable to one position for conditioning the switch for manual operation and to another position for conditioning the switch for operation by said switch machine, and means controlled by said dual selector for breaking said stick circuit when the switch 10 is conditioned for manual operation.

10 92. In a centralized traffic control system for railroads, an office and a station connected by line wires, means for transmitting distinctive codes over said line wires, a track switch at said station, a motor for operating said switch, normal and reverse circuits for said motor, code responsive means for selectively closing said circuits in response to different codes transmitted over said line wires from said office, two electro- 15 responsive devices including one in each said circuit, each operable when the current therein is abnormal to open said circuit, and means for again closing said motor circuit in response to a repeated operation of said code responsive means.

20 93. In a centralized traffic control system for railroads, an office and a station connected by line wires, means for transmitting distinctive codes over said line wires, a track switch at said station, a motor for operating said switch, normal and reverse circuits for said motor, code responsive means for selectively closing said circuits in response to different codes transmitted over said line wires from said office, two electro- 25 responsive devices including one in each said circuit, each operable when the current therein is abnormal to open said circuit, means responsive to the operation of said electroresponsive device for transmitting a distinctive code to said office, indication means at the office selectively responsive to such code, and means for again closing said motor circuit in response to a repeated operation of the code responsive means at said station.

30 94. In combination with a line circuit, a two-position device, transmitting means for transmitting indications corresponding to each position of said device over said line circuit, a stick relay, means for energizing said stick relay when the transmission of one of said indications has been completed, means for subsequently maintaining said stick relay until the transmission of the other of said indications has been completed and for then releasing said stick relay, a starting circuit effective when closed to initiate the operation of said transmitting means, and means closing said starting circuit when the device occupies a position different from that which it occupied when the last indication was transmitted by said transmitting means.

40 95. In a remote control system, an office and a plurality of stations connected by a normally closed line circuit, transmitting contacts at the office and at each station operable at times to transmit codes from the office to said stations or from a station to the office over said line circuit, means for prolonging the initial open circuit period of each code transmitted from the office only, means at the office for initiating the operation of the office transmitting contact, means at each station for initiating the operation of the transmitting contact at such station including a sectionalizing relay effective when operated to include the associated contact in the portion 45 of the line circuit extending to the office and to

5 open the portion of the line circuit extending to more remote stations until the code then being transmitted is completed, a lockout relay at each station selectively responsive to a prolonged opening of said line circuit, means controlled by each 10 said lockout relay when operated for releasing the associated sectionalizing relay in the event the office and a station or two stations start transmission at the same time, and means effective if said lockout relay and sectionalizing relay 15 are both operated to open the line circuit at such station until the associated sectionalizing relay releases to restore the line circuit from the office to more remote stations.

20 96. In combination with a railway switch adapted to be at times hand operated and at times to be power operated, controlling means at a remote office to govern power operation of the switch, manually controlled means located at the switch effective when operated to render 25 the switch responsive to hand operation and to render said controlling means ineffective to move the switch, and means effective when hand operation is concluded and said manually controlled means is restored to automatically transmit an indication impulse to the remote office for establishing an indication that control of the switch is restored to said controlling means.

30 97. In a centralized traffic controlling system of the selector type for controlling traffic on railroads, the combination with a line circuit connecting a central office and a plurality of way stations and including a line relay at said central office and at each of said way stations, of a series of stepping relays in said central office and at 35 each of said way stations, a primary relay in said central office for applying impulses to said line circuit, energizing circuits controlled by the line relay in said office for causing the stepping relays at said office to be energized sequentially 40 one relay for each impulse on said line circuit, and energizing circuits including contacts of said stepping relays for intermittently actuating said primary relay.

45 98. An impulse absorbing group of relays for centralized traffic controlling systems for railroads for delivering impulses only after a predetermined number of impulses have been received comprising, a series of stepping relays of the first order, a series of relays of a second order, 50 means for picking up and sticking up a relay of the second order during each successive operation of all the relays of the first order and for effecting repeat operation of said relays of the first order in response to impulses received, and 55 means for delivering the impulses as they are received when all of said relays of the second order have been stuck up.

60 99. An impulse absorbing group of relays for centralized traffic controlling systems for railroads for delivering impulses only after a predetermined number of impulses have been received comprising, a series of stepping relays of the first order, a series of stepping relays of a second 65 order, means for picking up and sticking up a relay of the second order during each successive operation of all the relays of the first order and for effecting repeat operation of said relays of the first order in response to impulses received, 70 means for delivering the impulses as they are received when all of said relays of the second order have been stuck up, and means for establishing message circuits by the impulses delivered.

75 100. In a train dispatching system of the selec- 75

tor type, the combination with a plurality of stepping relays successively picked up in accordance with stepping impulses applied to a line circuit connecting two spaced stations, a stick relay picked up when the last one of said stepping relays has been picked up, a stick circuit

for said stick relay, and a contact controlled by said stick relay for causing said series of stepping relays to again be picked up successively in accordance with stepping impulses on said line circuit.

LLOYD V. LEWIS.
